UNITED STATES PATENT OFFICE

1,966,748

BASEBALL GAME APPARATUS

Walter Z. Allen, Tulsa, Okla., assignor to Prairie Investment Corporation, Tulsa, Okla., a corporation of Oklahoma

Application August 29, 1930, Serial No. 478,760

81 Claims. (Cl. 273—89)

This invention relates to miniature automatic base ball game apparatus and has to do more particularly with a machine, or apparatus of the above character adapted to be manually controlled 5 for pitching and batting the ball, together with figures or runners automatically advanced on the bases according to the kind of hit that is made, and with scoring apparatus for the same.

The general object of my invention is to provide a machine or apparatus of the above character adapted to be played in a manner closely resembling an actual base ball game, and in which the results are determined largely by the skill of the player or players.

15 A further object is to provide a machine of the type referred to in which the playing field and all of the associated mechanism are enclosed in a case or housing, and are inaccessible to the operator, a transparent panel at the top of the 20 housing permitting the plays to be observed. The operating handles for controlling the pitching and batting devices extend to the outside of the housing, and the invention contemplates means rendering such handles normally inoperative and 25 the provision of coin-controlled mechanism for rendering the handles operative, upon deposit of a coin, for a predetermined number of plays or for a predetermined length of time.

Specifically, the present invention has for its 30 object certain improvements over the game apparatus disclosed in U. S. Patent No. 1,643,522, issued September 27, 1927, to Ezra B. Ropp. Before pointing out in detail the exact character of these improvements, it may be helpful to briefly 35 describe the general nature of the apparatus embodying the invention.

In this apparatus, as in the Ropp patent, a base ball field is provided having the usual outfield, 40 infield and diamond with base positions, together with a batting apparatus controlled by the operator and a ball feeding and pitching apparatus also controlled by the same or another operator. That is, the pitching apparatus is manually manipulated to pitch the ball over the surface of 45 the field toward a bat, which is swung by the manual manipulation of the operator. When the ball is hit it is knocked out into the field, preferably by rolling over the surface where it may drop down into any one of a number of 50 different control positions having electric contacts which advance runners over the bases according to the hit made. In the present form of my invention, one, two, three and four base hits may be made. Also sacrifice hits may be made, 55 or an out registered either by a strike or by hit-

ting the ball to certain positions in the infield or outfield. The men are advanced on the bases as in a regular game. That is, assuming the first ball hit is for one base, a runner is automatically advanced to first base. Should the next hit be 60 for two bases, the man on first is advanced to third and the batter advanced to second base, all automatically. Should the next hit be a home run, the two men on base will be advanced 65 around the bases to the home plate and as a result of the home run another player, that is the batter, makes a complete circuit of the bases. Thus as described, three hits have been made and these are all automatically recorded on the score board. Also three runs having been made, 70 they would be automatically recorded on the score board. Thus the game continues until the side at bat makes three outs, the outs also being recorded. Then the other side or opponent 75 player controls the batting device and continues until three outs are made. Outs and innings are automatically indicated, so that one can always tell at a glance the score of the game, the inning and the number of outs. Where two people 80 are playing the game, first one operates the batting device until three outs are made and then the opponent operates it, the other player doing the pitching. This continues up to the capacity 85 of the machine. In the present form of my invention the machine is designed to operate for five full innings, when it is automatically rendered inoperative and requires the deposit of another coin before it can be played again. It is to be understood, however, that my invention is 90 not limited to any particular number of innings, this depending upon the design of the mechanism.

Referring again to the Ropp patent, it will be seen that should the player or players for any reason fail to finish a game, after beginning one, 95 the apparatus would remain indefinitely with a partial score appearing on the registering device, and not in condition for a new game to be started. Thus, if the machine is constructed to shut off 100 and reset after 30 outs, corresponding to five innings, have been registered, and if the players should stop the game before this number of outs has been registered, difficulty would result. I propose to overcome this defect in the Ropp machine by providing means for automatically operating the registering mechanism at the end of a predetermined time interval, to complete the registration of the required number of outs to cause the machine to shut-off and restore itself 105 to its initial condition, ready for a new operation. 110

Thus, with my improved arrangement, the amount of play made possible by the deposit of a coin is limited either by the registration of a definite number of outs during the regular course 5 of the game, or by the lapse of a definite period of time, or both, so that, should, on the one hand, the players abandon the machine before completing the game, or, on the other hand, play the game abnormally slowly, the requisite additional 10 number of outs will be automatically registered at the end of the predetermined time interval, and the machine shut off. Hence it is impossible for an operator, either through inadvertence or intent, to cause my improved apparatus to remain 15 in any but a normal condition.

Another difficulty experienced with the Ropp machine is that trouble is frequently caused by the pitching of a second ball before the play initiated by the first ball is complete. An object 20 of the present invention is to obviate this difficulty by the provision of means for positively preventing the pitching of a second ball until all mechanism set in operation by the pitching of the first ball has finished its cycle of operation 25 and come to rest. This I accomplish by automatically locking the pitching device and maintaining it locked so long as the base running mechanism is in action. I also propose, in addition, to provide means for maintaining all field 30 contact circuits open during the progress of a play, so that should another ball accidentally enter any contact pocket, it would have no effect.

A further object of the invention is to devise 35 pitching mechanism which shall be much more simple and certain in its action than that of Ropp. To this end, I propose to actuate my improved pitching arm electrically, by means of a solenoid.

Still another object is to simplify and improve 40 the registering mechanism and the means for operating it. To this end I propose to actuate the registering mechanism both for runs, hits and outs, entirely electrically, thus doing away with the complicated and uncertain rods and pull wires heretofore employed.

45 In the Ropp machine, a mechanical switch is employed between third base and home which determines by its position whether a runner approaching home plate shall pass on around the bases beneath the playing field, or whether he 50 shall be placed in position to be elevated above the playing field in going from home plate to first base. I find that a better and simpler method of controlling the base runners can be carried out by having all runners passing home 55 plate remain in position to be elevated above the field, and to go to first base, and by providing a track switch between home plate and first base which determines, by its position, whether a given runner is elevated or whether he is kept 60 below the field.

A still further object of the present invention is the provision of improved and simplified movable track construction, and in this connection I contemplate the employment of an electromagnet for 65 holding the track in its operative position, such holding means being more positive and less likely to get out of order than the mechanical latch heretofore proposed.

While in my present machine I employ one, 70 two, three and four base hit magnets, generally the same as Ropp, as well as double advance and sacrifice hit magnets, an important object of my invention is to devise greatly simplified and improved mechanism by which such magnets control the base runners. In such improved mech-

anism I propose to so construct and arrange the parts that the moving elements comprise mechanical devices only, all coils and wiring remaining fixed or stationary, and in this way the transmission of current to such coils presents no 80 problem.

It has been further found that in the Ropp apparatus, the pitching mechanism will be rendered inoperative by a slight variation in the size of the balls. A further object of the present invention is therefore to devise pitching mechanism so designed that even a large variation in the size of balls will have no ill effects, or, in other words, that balls of different or random sizes can be successfully handled.

Still another feature of practical importance which I have in mind in the design of my improved machine is the elimination of brakes. This is made possible by using a constantly running motor, and by employing positive friction drive, and worm gearing which prevents over running, as well as by avoiding clutches of such a character as to possibly cause the parts to "drift" when the clutch is disengaged.

Another practical aspect of the invention which I have in view is the production of a machine of the character in question which does not necessarily have to be set level in order to operate. This is especially necessary on shipboard, and can be accomplished by the use of a special type of field 100 contacts.

In prior machines such as that of Ropp, where an electric motor is employed to drive the base running mechanism, it has been found that it is sometimes possible to register another "out" on the recording device even after current to the motor has been cut off by the termination of a game. I propose to cure this defect by providing an extra switch controlling the supply of current to all of the field contacts, and by opening this switch at the same time that the switch controlling the motor circuit is opened. Thus, immediately that the motor is shut off, no further operation of the registering mechanism is possible, and the pitching handle is also thereby automatically 115 locked.

Finally, in the design of my improved apparatus, I have in mind so devising and arranging the component parts that failure of any one mechanism or group of mechanisms will not tie up or 120 jam the entire machine. Thus, for example, should the improved sacrifice hit mechanism fail, for any reason, to operate, I intend that the rest of the machine shall continue to function, just the same, and this is true of most of the other individual mechanisms.

Other objects, features and advantages of the invention will hereinafter appear, as the description of the machine progresses, and, in order that the invention may be clearly understood, reference 135 is had to the accompanying drawings, forming part of this specification, in which drawings:—

Fig. 1 is a perspective view of the complete apparatus.

Fig. 2 is a fragmentary vertical section on an 140 enlarged scale showing the batting mechanism.

Fig. 3 is a similar vertical section showing the pitching mechanism.

Fig. 4 is a sectional plan view on the line 4—4 of Fig. 3.

Fig. 4, looking in the direction of the arrows, parts being broken away and parts being omitted for the sake of clearness.

Fig. 8 is an elevation of the device shown in Fig. 5 7, looking from the opposite side.

Figs. 9 and 10 are enlarged fragmentary vertical sections through a portion of the pitching mechanism illustrated in Fig. 3, the parts being shown in two different positions.

10 Fig. 11 is a plan view of the base running mechanism, on the same scale as Fig. 3, parts being in section and parts being omitted for the sake of clearness.

Fig. 11a is a fragmentary transverse section 15 through the switching device shown in Fig. 11.

Fig. 12 is a vertical section taken substantially on the line 12—12 of Fig. 11, looking in the direction of the arrows.

20 Fig. 13 is a vertical section taken substantially on the line 13—13 of Fig. 11, looking in the direction of the arrows, parts being broken away.

Fig. 14 is a fragmentary inverted plan view further illustrating some of the parts shown in Fig. 13.

25 Fig. 15 is a vertical section substantially on the line 15—15 of Fig. 11, looking in the direction of the arrows.

Fig. 16 is a sectional plan view taken substantially on the line 16—16 of Fig. 13.

30 Fig. 17 is a plan view of the driving and controlling mechanism.

Fig. 18 is a side elevation thereof, parts being in section.

35 Fig. 19 is a sectional plan view taken on the line 19—19 of Fig. 18 and illustrating the control mechanism.

Fig. 20 is a fragmentary vertical section substantially on the line 20—20 of Fig. 17, parts being omitted.

40 Fig. 21 is a fragmentary detailed elevation illustrating one of the control switches shown in Fig. 19, parts being in section.

Figs. 22 and 23 are respectively an enlarged plan view and vertical section showing the details of construction of one of the improved bearings 45 which I preferably employ.

Fig. 24 is a fragmentary elevation showing the coin controlled automatically operated starting and stopping mechanism for the machine.

Fig. 25 is a horizontal section on the line 25—25 50 of Fig. 24.

Fig. 26 is a vertical section taken substantially on the line 26—26 of Fig. 25, looking in the direction of the arrows.

55 Fig. 27 is a vertical section on the line 27—27 of Fig. 25, looking in the direction of the arrows.

Figs. 28 and 28a together constitute a rear elevation of the electrically operated scoring or registering mechanism.

60 Figs. 29 and 29a together constitute a front elevation of the same mechanism, the front panel being removed for the sake of clearness.

Figs. 30 and 30a together constitute a vertical section substantially on the line 30—30 of Figs. 65 29 and 29a, looking in the direction of the arrows.

Fig. 31 is a plan view on an enlarged scale showing in detail the twin switch mechanism illustrated in Fig. 29a.

70 Fig. 32 is a detailed fragmentary transverse section showing the means for releasing the locking pawls illustrated in Fig. 30.

Fig. 33 is a vertical section through one of the ball receiving openings or pockets hereinafter referred to and showing one of the field contacts 75 associated therewith.

Fig. 34 is a plan view of the improved timing mechanism which I prefer to employ.

Fig. 35 is an end elevation thereof.

Fig. 36 is a vertical section on the line 36—36 of Figs. 34 and 35; and

Figs. 37, 37a and 37b together constitute a diagram showing the electrical circuits embodied in the machine.

Referring to the drawings in detail and first more particularly to Fig. 1, my improved apparatus comprises a cabinet or casing 1 supported at a convenient height on legs 2 and having its sides closed by removable panels 3.

The top of the cabinet is closed by a glass or other transparent panel 4, below which lies the playing field 5. This playing field may be formed of a slab or plate of any rigid material, preferably covered with a sheet of felt or the like.

In order to adequately illuminate the playing field, I preferably provide at one or both sides thereof a lamp 1^d (see Fig. 12) concealed within the cabinet, and disposed opposite a slot 1^e in the wall 1^a, through which the light may shine upon the field.

The playing field has at one corner a slot 6 extending through the same and following the base lines, so that the slot defines the usual diamond. This slot, however, is not continuous but preferably terminates at each side of home plate so that the field between the pitcher's box and the bat 105 presents an unbroken surface.

Distributed over the field are a plurality of control devices shown as pockets or openings 7, into which openings hit balls are adapted to drop. A series of other similar openings or pockets 8 is also disposed around the margin of the playing field, which pockets receive the hit balls which do not enter any of the other pockets. Adjacent the base lines from home plate to first base and from home plate to third base are preferably disposed foul troughs 9 into which foul balls may roll. From these troughs extend chutes 9^a which deliver the balls into a pan or receptacle 66, hereinafter described and extending beneath the playing field.

One of the ball receiving pockets or openings is located immediately behind home plate, as indicated at 10, a pitched ball entering this opening or pocket whenever the batter fails to hit it, or, in other words, makes a strike.

120 Mounted adjacent home plate is a bat 11 arranged to swing in a horizontal plane about a vertical axis, as hereinafter described, and operated by means of a knob or handle B projecting through the side of the cabinet.

125 A pitching mechanism is provided, as herein-after described, and is arranged to pitch or roll a ball over the field from the pitcher's box PB toward home plate, this pitching mechanism being controlled by means of a pitching crank or handle P located as shown in Fig. 1.

130 At the corner of the playing field opposite home plate I provide an automatic scoring or registering device designated in its entirety by the reference numeral S and hereinafter more particularly described.

135 It is proposed to control the apparatus by the deposit of a coin, and a suitable coin controlled device is indicated at C. This device is operatively connected to means for starting and stopping the machine, as will hereinafter appear.

Batting device

140 Referring now more particularly to Fig. 2 in which the batting apparatus is illustrated in de-

80

85

90

95

100

105

110

115

120

125

130

135

140

145

150

tail, it will be seen that the bat 11 is rigidly mounted at the upper end of a vertical shaft 12 mounted in a bearing 13 extending through the playing field and journaled at its lower end in a bracket 18. A collar 14 is fixed to the shaft 12 below the bearing 13 by means of a set screw 15, and a bevel gear 16 is secured to the lower end of the shaft by means of a set screw 17, the hub of this gear resting upon the bracket 18 and thus supporting the bat in position.

It will be seen that the bat extends parallel with and close to the playing field and that it may be swung in a complete circle, a slot 18 being provided in the adjacent wall 1^a, to permit this. Furthermore, I contemplate adjusting the bat vertically to a slight extent so that its point of contact with the ball, relative to the center of the ball, may be somewhat varied. This I accomplish simply by loosening the set screws 15 and 17 and raising or lowering the shaft 12 to the desired extent and then tightening the said screws again. By thus adjusting the height of the bat above the field, its effect on a hit ball may be varied. If the bat is below the center of the ball it will tend to lift the ball above the field and cause it to bounce, while if it is above the center of the ball it will, as is obvious, cause the ball to hug the field closely.

The shaft 12 is rotated to swing the bat by means of a gear 19 meshing with the gear 16 and carried by a shaft 20 journaled in the bracket 18, a collar 21 being employed to hold the shaft in place. A similar shaft 22, carrying the batting knob B, is journaled in the panel 3 in substantial alinement with the shaft 20 and is connected thereto by means of a flexible coupling constituting a universal joint, this coupling being illustrated as comprising a short section of rubber hose 24 secured to the adjacent knurled ends 23 of the two shafts by means of clamps 25. This detachable flexible joint not only permits the panel 3 to be removed but also improves the operation of the bat and avoids the necessity of having the two shafts 20 and 22 in accurate alinement.

Pitching mechanism

Referring now more particularly to Figs. 3 to 10, inclusive, I will describe in detail my improved pitching mechanism.

The pitching crank P is rigidly secured to the upper end of a vertical shaft 26 journaled in the top of the cabinet. This shaft carries at its lower end a cylindrical block 27 having at its bottom a reversely beveled projection 28. This projection is adapted to fit in a V-notch formed in a similar block 29 rigidly secured to the upper end of a shaft 29^a forming a continuation of the shaft 26 and journaled at its ends in brackets 30 and 32 secured to the bottom 33 of the cabinet, the bracket 30 carrying a lubricating bearing 31 similar to those hereinafter described.

Projecting upwardly from the block 29 is a sleeve or cylinder 34 in which the block 27 loosely fits, and a compression spring 35 surrounds the shaft 26 and is enclosed within the sleeve or cylinder 34. This spring is confined between the end of the block 27 and a washer 36^a held down by screws 36 or the like at the upper end of the sleeve 34, so that it exerts a downward pressure on the block 27 holding the projection 28 thereof in engagement with the notch in the block 29.

This arrangement, just described, provides a safety or slip clutch between the operating crank P and the pitching mechanism itself. This

clutch is capable of transmitting sufficient torque to operate the pitching mechanism under normal conditions, but should such mechanism be locked, as hereinafter described, or for any reason become jammed, the clutch connection will slip, due to the yielding of the spring 35, and thus prevent the mechanism from being damaged by any attempt to improperly operate it.

Rigidly secured to the shaft 29^a is a bevel gear 37 meshing with another bevel gear 38 secured to a horizontal shaft 39 journaled in the bracket 30. This shaft carries a ratchet wheel 40 with which a locking pawl 41 pivoted at 41^a (see Fig. 5) is adapted to engage. This pawl is held by gravity in locking position and when in this position it is impossible to rotate the shaft 39 in an operative direction. The locking pawl is adapted to be lifted and released by means of an electromagnet 42 maintained above the same by means of a bracket 43, and energized by means hereinafter described.

Rigidly attached to the end of the shaft 39 is an enlargement 44 having a central bore or socket 45. (See Fig. 6.) A shaft 46 is loosely received within this socket 45 and is journaled in bearings 52 and 53 carried by the side plates of a casing 54, more clearly shown in Figs. 7 and 8.

A pin 47 projects radially from the shaft 46 and works freely in a slot 48 formed in the enlargement 44, and a helical spring 49 surrounds this enlargement and is anchored thereto at one end, 50, while its other end is looped around the pin 48, as shown at 51.

From the foregoing, it will be obvious that as the shaft 39 is rotated in a right handed or clockwise direction, the spring 49 is wound up or placed under tension and exerts a yielding driving action against the pin 47, tending to rotate the shaft 46.

Referring now to Fig. 7, it will be seen that in side of the casing 54, there is mounted upon the shaft 46 a cam 57 shaped as shown in dotted lines. Bearing against this cam is a roller 58 carried at the lower end of a vertically extending plunger 59 mounted to reciprocate in a block at the upper end of the casing 54 and having pins 60 projecting from opposite sides thereof, and working freely in guide slots 61 formed in the side walls of the casing. Thus the plunger 59 is prevented from rotating. In order to hold the roller 58 firmly in contact with the periphery of the cam 57, I preferably attach to one or both of the pins 60 one or more helical springs 62, as clearly shown in Fig. 8.

The playing balls are indicated at 64. These may be of steel, similar to ordinary ball bearing balls, or of other metal, or they may be formed of celluloid or other plastic and non-conducting material, as they do not serve to form any part of an electric circuit.

The balls 64 are fed to the pitching apparatus through a chute 63 (see Fig. 7), which chute extends from the pan 66, heretofore referred to and illustrated in Fig. 1. It will be understood that, as in the Ropp patent, this pan extends underneath the playing field and receives all balls passing through the various openings or pockets. The pan slopes from all directions toward a discharge opening, with which opening the inclined chute 63 is connected. Thus all balls passing through the control pockets or foul troughs in the playing field fall into this pan and find their way by gravity into and through the chute 63. From the lower end of this chute the balls are delivered into a chamber 65 immediately above the

plunger 59. As the shaft 46 rotates, the cam 57 reciprocates this plunger and causes it to push the balls one at a time upwardly from the chamber 65 out through a vertically extending tube or conduit 67. Pawl 68 is pivoted at 69 adjacent the lower end of this conduit, the pawl being yieldingly held in the position shown in Fig. 7 by means of a spring 70 and serving to engage the lowermost ball in the conduit 67 and thus support the column of balls within the same, as each ball moves past it.

The upwardly extending tube 67 is connected at its upper end with the lower end of a conduit 71, which continues upwardly to a point just beneath the playing field and terminates in a laterally disposed mouth or discharge opening 72 (see Fig. 9).

A pitching arm 74 is pivoted at 75 just below the playing field and is provided at its upper end with a cup or socket 73, adapted to receive the ball to be pitched. As clearly shown in Fig. 9, this cup is normally disposed immediately below the discharge opening 72 so as to receive the balls therefrom.

At the opposite side of the pivot 75 from the cup 73, the pitching arm is provided with an arcuate toothed rack 76 adapted to mesh with a straight rack 77 formed at the upper end of a reciprocating rack bar 78 slidable in a guideway 79. It will thus be seen that when the rack bar 78 is moved downwardly, the pitching arm 74 is swung about its pivot 75 upwardly and forwardly to the position shown in Fig. 10, thus pitching the ball along the surface of the playing field, as indicated by the arrow, and in a manner generally similar to Ropp. There is this fundamental difference, however, between the two mechanisms. In the Ropp machine, the balls are fed upwardly at the side of the pivot opposite the cup carried by the pitching arm, and in the plane of said arm, while in my improved construction the conduit up which the balls are fed is disposed on the same side of the pivot as the cup and is outside of the plane of the arm. Furthermore, in my improved arrangement, the balls are delivered laterally into the cup, or in a direction at right angles to the plane of movement thereof.

As a result of this improved arrangement, slight variation in the size of the balls has no bad effect. In fact, the balls can vary 5 to 10 per cent in diameter without interfering with the operation of the mechanism. Thus, the necessity for having balls accurately similar in size is obviated.

As in the Ropp machine, I employ above the pitching arm a trap-door normally flush with the surface of the playing field. This trap-door is indicated at 80 and is shown as pivoted at 81. In the present construction, the door is provided with a tail piece 82 projecting at right angles thereto, and this tail piece is connected with the pitching arm itself by means of a link 83 pivoted to the arm at 84. The link is of such shape as to extend beneath the cup of the pitching arm when in normal position, as shown in Fig. 9. This link provides a positive connection between the trap-door and pitching arm so that they move together at all times.

The lower end of the rack bar 78 is pivotally connected by means of a link with a horizontal lever 85 pivoted at 86 (see Fig. 3). A spring 87 secured to this lever and anchored at its upper end to a fixed support 88 tends to maintain the lever in the position shown in the drawing.

The extreme end of the lever 85 is connected by means of a link 89 with the upper end of the plunger 90 of a solenoid 91 carried by brackets 92 clamped to a vertical post 93. Thus, when the solenoid 91 is energized the core 90 is pulled downwardly, thus reciprocating the rack bar 78 and swinging the pitching arm upon its pivot with a pitching action.

Extending through the wall of the casing 54 and mounted to slide through this wall and through a bracket 98, is a rod 95 carrying at its inner end an enlarged head 94 positioned in the plane of the cam 57 and roller 58. Outside of the casing, this rod carries a switch device comprising adjacent blocks of insulation and of metal 96 and 97, against which a pair of spring contacts 99, and a third contact 99^a, all mounted on an insulating bracket 100, are arranged to bear. The spring contacts 99 are included in the circuit of solenoid 91 so that when the insulation 96 is between said contacts, the circuit is broken, but when the metal portion 97 is brought between the contacts, the circuit of the solenoid is closed. The function of contact 99^a will be hereinafter described.

From the foregoing, it will be seen that as the cam 57 rotates in a right hand or clockwise direction, as indicated by the arrow in Fig. 7, the cam will first lift the plunger 59 to elevate the column of balls in the tube 67 and feed one ball 105 to the pitching arm, and then, as the high point of the cam passes under the roller 58, it will engage the head 94 of the switch rod 95 and shift the switch toward the right, thus closing the circuit of the solenoid 91. It will be further observed that, owing to the tension generated by the spring 49, the cam 57 will clear the roller 58 and strike the head 94 of the switch rod 95 suddenly with a snap action. The movement of the switch with this snap action is the purpose 115 of the spring 49 and associated parts.

As the core 90 of the solenoid moves downward, when the solenoid is energized, a non-magnetic extension thereof 90^a strikes upon a block 101 carried by one arm of a bail 102 pivoted 120 at 103 to the bottom of the cabinet and having its other arm 104 extending vertically upward into the plane of movement of the switch rod 95. Thus, at each energization of the solenoid 91 the plunger 90^a strikes the block 101 and 125 swings the arm 104 to the left, thus engaging the end of the switch rod 95 and pushing it back again into the position shown in Fig. 7. In other words, the above described mechanism constitutes automatic means for interrupting the circuit of the solenoid immediately after each energization thereof, so that the current that flows through the solenoid is only momentary.

Base running mechanism

Taking up now the mechanism for supporting the base running figures and advancing them around the bases, reference will be had more particularly to Figs. 11 to 21, inclusive.

Suspended below the playing field and connected therewith by a plurality of posts or brackets 105, is a platform 107, and supported above this platform by means of shorter posts 106, is a second platform 108, the central portion of these platforms being cut away, as shown in Fig. 11.

Under each of the base positions on the playing field, are disposed vertical shafts 111 and 112 journaled in bearings 113, supported by the platforms 107 and 108, one of these shafts, namely, the shaft 111 being extended downwardly below 150

the platform 107 and serving as a driving shaft, as hereinafter described.

The particular type of bearings which I prefer to employ throughout the machine and which are indicated in Fig. 12 at 113, are shown more in detail in Figs. 22 and 23. Each of these bearings comprises a circular drum having a central boss 115 through which the shaft freely passes, this boss being provided with a plurality of radial holes in which are fixed wicks 117. The drum 113 is provided with a cover plate 116 on which rests a thrust collar 114 secured to the shaft, such as 111. The interior of the drum being packed with absorbent material and filled with oil, the lubricant is carried to the shaft by the wick 117 and I have found that this type of bearing remains in set condition without attention for long periods of time.

Secured to each of the vertical shafts 111 and 112 are a pair of sprocket wheels 110, one located adjacent each platform 107 and 108. Passing around the two sets of sprocket wheels are a pair of sprocket chains 118, this part of my machine being substantially the same as that of Ropp.

Secured to the two chains 118 are four vertical guides or figure holders being spaced apart a distance equal to the distance between bases. Each guide or holder has a vertical slot 120 formed in the outer side thereof in which slot 120 freely slides a pin 121 set into the lower part of a base running figure 122, which figure is adapted to reciprocate vertically in the guide or holder, as in Ropp.

The shaft 111 is driven by means of an electric motor 123 which motor preferably runs constantly from the time the coin is deposited until the machine automatically shuts off, as described. Referring more particularly to Figs. 17 and 18, the motor 123 has a shaft 124 connected by means of a suitable coupling 125 to the shaft 126 of a generator or dynamo 127. This generator is employed to furnish the current necessary to operate the field contacts and associated controlling magnets and solenoids and it is preferably of low voltage. In practice, it is convenient to wind the motor 123 for 110 volts and the generator 127 for 32 volts, thus making it possible to use standard 32 volt lamps on the generator circuit. While, of course, the current is energizing, the field and control circuits might be obtained from some other source, such as primary or secondary batteries, I prefer the above described arrangement of motor driven generator, as cheaper and simpler.

Secured to the shaft 126 is a friction pulley 128 and, spaced a short distance away is a similar friction pulley 129 secured to the shaft of a transmission box 130. The two pulleys 128 and 129 are preferably provided with V-shaped grooves on their periphery.

Extending through the transmission box 130 and driven by suitable reduction gearing inside of the same, is a horizontal shaft 131 carrying at one end a bevel gear 132 meshing with a similar gear 133 secured to the lower end of the shaft 111, such shaft being journaled in a bracket 134.

Disposed between the two pulleys 128 and 129, and adapted to engage the same, is a friction wheel 135 preferably formed of hard fiber or the like and having a wedge-shaped periphery adapted to enter the grooves in the pulleys 128 and 129. This friction wheel 135 is journaled at 136 between the arms of a bifurcated swinging lever 137 pivoted at 138 to a fixed bracket 139. The upper end of this lever is connected by a link 140 with

the plunger 141 of a horizontally disposed solenoid 142 supported on a bracket 144. The portion 141 of the plunger is of non-magnetic material and is secured to a magnetic core 143 projecting from the opposite end of the solenoid so that, when the solenoid is energized the plunger and lever are moved to the right, as viewed in Fig. 18. This swings the wheel 135 upwardly and forces it in between the friction pulleys 128 and 129, thus transmitting power from the driving pulley 128 to the driven pulley 129, thereby, through the gearing above described, causing the rotation of shaft 111. When this shaft rotates, the chains 118 are driven and the base running figures are caused to advance around the bases. The extent of such advance is, of course, determined by the length of time that the operating solenoid 142 remains energized, and this, in turn, is governed by the controlling mechanism now to be described.

At the end opposite the gear 132, the shaft 131 carries a bevel pinion 145 which meshes with a bevel gear 146 secured to the end of a horizontal shaft 147 supported on a bracket 148. This shaft 147 carries at its other end a bevel pinion 149 meshing with a large horizontal bevel gear 150 secured to a vertical shaft 151 journaled in a platform 152 supported by posts 153, and at its lower end in a bearing 113 preferably similar to that illustrated in Figs. 22 and 23. The shafts 131 and 147 are also preferably mounted in lubricating bearings 131^a and 147^a of any desired type, as indicated in Fig. 17.

Positioned on a circle concentric with the shaft 151 and disposed radially thereof and 90° apart are a series of base hit magnets 155 carried by brackets 154 fixed to the platform 152. Thus, these magnets are stationary and the circuit connections to them can be made without difficulty. Secured to the shaft 151 so as to rotate therewith is a drum 156 having upper and lower flanges 157 and 158 between which are mounted a series of four plungers 159, also spaced 90° apart, so as to register with the base hit magnets. These plungers pass through openings in the flanges 157 and 158 and are capable of free reciprocatory movement.

The upper end of each plunger is preferably reduced in diameter, as shown at 160, (see Fig. 20) and this reduced end passes upward through an opening in one arm 161 of a bell crank lever pivoted at 163 to the flange 157. The other arm of this lever 162 extends substantially vertically and constitutes an armature for the base hit magnets. Each plunger 159 has ad-

jacent the arm 162 of the corresponding lever a notch 164, and the lever arm 162 carries a latch 165 adapted to engage such notch and thus hold the plunger in elevated position, as shown at the right of Fig. 20. In order to prevent the plunger from rotating on its own axis, one side of the reduced portion 160 is preferably flattened, as shown at 160^a, and a transverse pin 160^b extends through the arm 161 adjacent such flattened portion.

In order to assist gravity in forcing the plunger downwardly when the latch is released, I surround the reduced portion 160 with a helical spring 166 which bears at its upper end against the lever arm 161 and at its lower end against a shoulder 159^a on the plunger.

The lower end of each plunger 159 carries a metallic contact 168, shown as wedge-shaped, and insulated from the body of the plunger by means of a block of insulation 167. These contacts 168 are adapted to engage and bridge the gap between two arcuate spaced concentric contact strips 169 and 170 supported on the platform 152. which

platform is preferably of insulating material. When any one of the contacts 168 engages and bridges these strips, they are, of course, electrically connected and the circuit of which they 5 form a part is completed.

By reference to Fig. 19, it will be seen that the contact strips 169 and 170 are not complete rings but that they are broken at one point to provide a gap 171. By reference to Figs. 19 and 20, it will 10 be further seen that adjacent this gap one end of the strips 169 and 170 is inclined upwardly to form a ramp, as indicated at 172. The height of this ramp is such that the contacts 168, when the drum 156 is rotated, ride up the ramp and are 15 thereby elevated to a sufficient extent to cause the latches 165 to engage in the notches 164 and thus lock the plunger in elevated position.

From the foregoing, it will further be understood that when the operating magnet 142 is energized to force the friction wheel 135 into position to cause the shaft 111 to rotate, the drum 156 is driven in synchronism with the chains 118 carrying the base running figures, so that these figures and the plunger 159 move through exactly 25 equal angles.

Also, it will be clear that the lever arms 162 are located adjacent and constitute armatures for the respective base hit magnets and that the gap 171 is disposed immediately adjacent one of the 30 magnets, to wit, the four base hit magnet. Thus, when any one of these magnets is energized, the corresponding latch 165 will be released and the corresponding plunger 159 will drop bringing the contact 168 into engagement with the strips 169 35 and 170, and as the drum revolves this contact will eventually ride up the ramp 172 and be again latched or locked in elevated position so that as it moves beyond the ramp it will not drop down again into engagement with the strips. Thus, 40 if, as will hereinafter appear, the contact strips 169 and 170 control the circuit of solenoid 142, the energization of any base hit magnet will cause such solenoid to operate to bring the friction drive into action and to cause the drum 156 45 to rotate and, when the contact runs off of the ramp 172 and is automatically locked up, as described, the circuit to the solenoid 142 is broken and a rotation of the drum, and likewise of the base running chains 118, immediately ceases. 50 Thus, the drum will always come to rest with the plungers 159 in the relative position shown in Fig. 19, in which position each lever arm 162 is directly in front of the corresponding base hit magnet and in position to be attracted thereby.

In order to perform certain necessary circuit controlling operations, hereinafter described, I find it necessary to provide a series of switches so located as to be actuated by the plungers 159 as they travel around. The construction of these 55 switches is clearly shown in Figs. 19 and 21. Each switch comprises a block of insulation 173 to which is pivotally secured at 176 another block of insulation 175, this second block having rigidly secured to the under side thereof a metallic contact strip 174 preferably provided on its edge with humps 174a. Arranged to be engaged by these 60 humps are a pair of contact springs 177. It will be understood that the inner edge of the blocks 175 is so disposed as to be engaged by the side of the plungers 179, as shown in Fig. 21, and this engagement results in swinging the block about its pivot and in pressing the humps of the contact strip 174 against the contact spring 177, thus closing a circuit between these springs.

75 As shown in Fig. 19, it is necessary to employ

three of these special switches, all supported by the platform 152, one being located between the one base hit and two base hit magnets, another between the two base hit and three base hit magnets and the third between the three base hit 80 magnets and four base hit magnets. In Fig. 19, these magnets are designated 1B, 2B, 3B and 4B, respectively. As will more clearly hereinafter appear, the three sets of contact springs 177 are all connected in parallel, and to this end a wire 178 85 connects with one spring of each pair, while a wire 179 connects with the other spring of each pair.

In addition to the mechanism for supporting and advancing the figures around the bases, I, 90 like Ropp, provide means for selectively elevating the figures above the playing field. Unlike Ropp, however, I have devised means for elevating a base runner to one level if a sacrifice hit is made and to a different level if a base hit is made. 95

Referring to Fig. 13, I provide, beneath the playing field and between home plate and first base, an upwardly inclined guide or runway 180, the inclined portion connecting with a horizontal portion 181 which extends to a point beneath first 100 base and there terminates, as indicated at 182 in Fig. 16. The entrance to the inclined runway 180 is controlled by means of a bevel pointed track switch 183 pivotally mounted on a vertical shaft 184 (see Fig. 13). Opposite the beveled point, 105 this switch has a tail piece 185 which, when in one position, extends into the pathway of the figure guides 119 so as to be engaged thereby to swing the switch on its pivot.

When the switch 183 is in the position indicated in full lines in Figs. 13 and 16, it is obvious that the pin 121 of an approaching figure will ride up the beveled point of the switch and thence onto the inclined runway 180, thus elevating the figure above the field. When, however, the switch 110 183 is swung to the position indicated in dotted lines in Fig. 16, its point lies beyond the path of travel of said pin and consequently the advancing figure is not elevated but proceeds around the bases beneath the playing field and invisible to 120 the players, the bottom of the figure resting upon the platform 107 and being supported thereby.

At the top of the inclined runway 180 is located another track switch 186, similar to the switch 183, pivoted to swing on a vertical shaft 187 and 125 having a tail base 188. Just above this switch is located a second horizontal runway 189, and this switch determines by its position whether the pin 121 of an advancing player, arriving at the top of the inclined runway 180, shall be further elevated to the upper runway 189 or whether it shall continue on the lower runway 180. If it continues on the lower runway, the pin slips off of the end 182 thereof and the base runner drops out of sight beneath the field upon reaching first base.

In order that the base running figure passing along the upper runway 189 toward first base may register a hit on the scoring apparatus, I provide adjacent this runway a hit switch. This comprises a body 190 of insulating material pivoted at 191 in such a manner that the pin 121 of an advancing figure will engage underneath and lift the same. A contact strip 192 is secured to the upper face of the body 190 and is adapted to engage a pair of contact springs 193 and 194 carried by an insulating block 195. These springs are suitably connected with the electric registering device hereinafter described.

It will be noted that this hit switch is oper-

ated only by base running figures traveling on the upper runway 189. When the pin of such figures travels on the lower runway 181, it is obvious that the figures will pass by the switch 5 without operating the same.

In order that a base running figure, the pin of which has been elevated to the runway 189, may continue around the bases above the field, I provide track sections between first and second 10 bases, between second and third bases and extending from third base toward home plate, these three track sections lying in the same horizontal plane with each other and with the upper track or runway 189 so that a continuous runway extending around the bases is provided. (See Fig. 11).

The track section extending between first and second bases comprises a strip or flange 196 secured to and projecting inwardly from a bar 197, this bar being pivotally supported at its ends, as indicated at 198 in the sides of the posts 105. Similarly, the track section extending between second and third bases comprises a strip or flange 202 secured to and projecting inwardly 25 from a bar 201 pivotally supported at its ends in the posts 105. Also the track section extending toward home plate from third base comprises a strip or flange 206 secured to and projecting inwardly from a bar 205 pivotally supported between one of the corner posts and another post 30 105 located between third base and home plate. To the adjacent ends of the bars 197 and 201 are secured bevel gears 199 and 200, respectively, which are in mesh with each other, and to the adjacent end of the bars 201 and 205 are secured 35 bevel gears 203 and 204, respectively, which are in mesh. Thus it will be seen that all of the sections of the runway from first base around beyond third base are pivotally mounted and 40 geared together so that they all turn in unison.

From the foregoing, and especially from an inspection of Fig. 15, it will be seen that the pins 121 of the base running figures rest upon the strips or flanges of the various runway sections 45 and that if these runway sections be rotated on their pivots so as to cause these flanges to move downwardly and outwardly, the pins will be disengaged therefrom and the base running figures will be dropped to the bottom of the guides and 50 disappear from above the field. In other words, when the runway sections are turned on their pivots the base running figures are "dumped" off.

It is, of course, necessary that all base running figures coming in toward home plate from third 55 base be lowered beneath the field, and for this purpose I provide adjacent the end of the runway section 206 a downwardly inclined runway section consisting of a pair of spaced strips 207 between which the pin 121 of the figures is adapted 60 to pass. It will be seen that the figures are thus lowered to a point at which the bottom end thereof rests upon the platform 107, and the figures slide along on this platform as they pass around home plate from the end of the runway 207 until 65 they reach the track switch 183. It will be further noted that all figures approaching the track switch 183 are at the same level and all are in condition to be elevated thereby.

In order that the base runner coming in toward 70 home plate from third base may score runs on the registering device, I provide a run switch quite similar to the hit switch above described. This is clearly shown in Fig. 15 and comprises a bar 208 of insulating material pivoted at 209 adjacent the runway section 207 and so disposed

that the pin of an advancing figure will pass between this bar and one of the strips of the runway 207, and thus swing the bar on its pivot. The bar carries a metal facing which is adapted to engage a pair of spring contacts 210 and 211 connected with electrically operated run registering mechanism, as hereinafter described. 80

The above mentioned pivoted runway sections are turned on their pivots and controlled by the following mechanism. An arm 212 is secured 85 to a vertical shaft 213 (see Fig. 16) in such position that it projects into the path of the traveling figure holders 119. Also secured to this shaft 213 is another arm 214 connected by a link 215 with a bell crank lever 216 (see Fig. 12) pivoted at 217 to a bracket 223, all of which parts are of non-magnetic material. A link 218 pivotally connects the bell crank lever 216 with a lever 219 rigidly secured to one of the pivoted runway sections, namely, the section 201. It will, therefore, 90 be obvious that as the arm 212 is engaged by an advancing figure holder and the shaft 213 thus rocked, the link 215, bell crank lever 216 and link 218 will be moved to the position shown in Fig. 12 in which the runway strip or flange 202 is 100 horizontal. The runway sections are normally held in this position by means of a magnet 222 supported by the bracket 223 and serving to hold the lower end of the bell crank lever 216 by direct magnetic attraction. Thus, as long as this magnet 105 remains energized, the runway sections are maintained in the figure supporting position shown, but when the magnet 222 is de-energized it releases the bell crank 216 and permits the weight of the base running figures to rock the 110 runway sections on their pivots, thus dumping the figures off. This dumping action is assisted and rendered more certain by a spring 220 secured at one end to the bell crank lever 216 and at the other end to a fixed support 221. 115

From the foregoing, it will be seen that the runway sections are moved to figure supporting position by the engagement of the figure guides with the lever 212 and are held in such position by the magnet 222, and further, that upon de-energization of this magnet, all of the runway sections simultaneously turn to figure dumping position. 120

I have previously described my improved means for elevating the base running figures to operative position above the playing field, and for raising them to either one of two different levels. I will now describe the means for controlling this elevating mechanism. 125

Referring again to Figs. 13, 14 and 16, there is 130 secured to the lower end of the shaft 184 carrying the track switch 183 a locking plate or segment 224, having a notch 225 in its edge adapted to be engaged by a latch 226 pivoted at 227 to a fixed bracket and urged toward the locking segment by means of a spring 228. A second spring 229 secured to the segment and to a fixed support tends to turn the segment, when released from the latch, to the position shown in dotted lines, in which position the switch 183 is in its inoperative position, as shown also by dotted lines in Fig. 16. 135

The latch 226 is disengaged from the locking plate 224 under certain conditions by the pull of an electromagnet 230 supported adjacent the 140 latch by means of a bracket 231. The circuit over which this magnet is energized will be hereinafter described. 145

To the lower end of the shaft 187 carrying the track switch 186 is secured a locking plate or seg- 150

ment 232 similar to the segment 224 and having a notch 233 adapted to be engaged by a latch 234 pivoted at 235. A spring 236 tends to hold the latch in engagement with the segment and a second spring 237 tends to turn the segment, when released from the latch, into the position shown in dotted lines in Fig. 14, in which position the track switch 186 is inoperative to elevate the base running figures.

10 The latch 234 is released under certain conditions by the pull of an electromagnet 238 also mounted on the bracket 231.

In addition to operating the track switch 186, the magnet 238 also operates a circuit controller. 15 To this end an armature 239 is provided adjacent the pole of the magnet opposite the latch 234, such armature being pivoted on a non-magnetic post 240 carried by the bracket 231. The free end of the armature 239 carries a block of insulation 241 in which is set a metallic conducting ring 242 adapted, when the armature is moved toward the magnet, to be engaged by three spring contact fingers 243, 244, and 245 supported on and distributed around a block of insulation 246, 20 co-axial with the block 241. Thus, when the armature is in the position shown in Fig. 11, the circuits controlled by the contact fingers 243 to 245 are open, but when the armature is energized, these three contact fingers are connected 25 with each other through the ring 242, and the circuits controlled thereby are accordingly closed. The exact nature of these circuits will be hereinafter described in detail.

35 Starting and stopping mechanism

The coin controlled means for starting the machine and the automatic means for stopping it will now be described in detail. Referring more particularly to Figs. 24 to 27, inclusive, the coin controlled device is designated, as in Fig. 1, by the reference character C. It consists of a casing 248 having a coin slot 248^a through which casing extends a horizontally slideable bar 247 having at its free end a finger hold 246 by means of which it 40 may be manually actuated. This bar is normally locked by suitable coin operated mechanism inside of the casing 248, which, as shown, comprises a latch 248^b pivoted inside the casing at 248^c. This latch has a lug 248^d adapted to engage a notch 247^a in the bar 247. A spring 248^e presses the latch toward the bar. A lug 247^b on the bar 247 is arranged to engage behind the coin X, and carry it along as the bar is pulled, and the coin engages a tail piece 248^f on the latch, 45 and thus swings the latch clear of the bar. The coin then drops into a chute, (not shown).

Secured to the other end of the bar 247 is an angle bar 249 to which is pivoted a latch 250 normally held against a stop pin 251 by means of a spring 252. This latch is adapted to engage over a pin 253 carried at the upper end of a lever 254 pivoted at 255 to a bracket 256. The lower end of this lever is pivotally connected to a rod 257 slidably mounted in a U-shaped bracket 258 and carrying a block of insulation 259 in which are mounted two spaced annular contact rings 260 and 261. This block of insulation having the annular contacts constitutes part of a double master switch, the ring 260 being arranged 50 to cooperate with a pair of spring contacts 262 to control one circuit and the ring 261 being adapted to cooperate with a pair of spring contacts 263 to control another circuit. These circuits will be hereinafter described in detail, but it may be 55 pointed out now that one is the main circuit to

the motor and the other is the circuit from the generator. The spring contacts 262 and 263 are mounted at their upper ends on a block of insulation 264 supported by brackets 265.

60 The end of the rod 257 opposite the lever 254 is pivotally connected to one end of a catch 266 pivoted at 267 to a suitable bracket, the parts being urged to the position shown in the drawings by means of a spring 268 connected at one end to a fixed support and at the other end to the catch 266.

65 The upper end of this catch has a notch adapted to be engaged by a horizontal pivoted latch 269, this latch being disposed immediately below and adapted to be lifted by an electromagnet 270 held between brackets 271 and 272 carried by a vertical plate 273.

70 Also, secured to the bar 249 is one end of a link 274 connected at its other end to a crank arm 275 rigidly attached to the upper end of a short vertical shaft 276 journaled in spaced brackets 277 and 278 secured to the plate 273.

75 Fixed to the lower end of the shaft 276 is a cam disk 279 having a cam face 280 (see Fig. 27) up which is adapted to ride a pin 281 carried by a vertically extending bar 282 mounted to reciprocate freely through openings in the brackets 277 and 278, and yieldingly held down by a spring 283. To this bar are pivotally connected the ends of two crank arms 284 and 286 (see Fig. 26) 80 rigidly attached respectively to rock shafts 285 and 287, forming part of the registering mechanism hereinafter described and illustrated in other figures.

85 From the foregoing, it will be understood that 110 the apparatus as shown in Fig. 24 is in its normal or inoperative position with current entirely cut off from the machine. When it is desired to operate the machine, the operator places a coin in the coin slot 248^a and pulls the bar 247 to the left, thus causing the latch 250 to engage over the pin 253. The operator then pushes the bar 247 to the right again, thus moving the lever 254 over toward the right and pulling the bar 257 toward the left, thereby positioning the contact rings 260 and 261 between the contact springs 262 and 263 respectively. This closes the two main circuits supplying current to the motor and to the control devices respectively, and the machine is in condition to play. The rod 257 is 115 locked in circuit closing position by means of the engagement of the latch 269 with the catch 266. As hereinafter more particularly described, means are provided for energizing the magnet 270 either after a predetermined number of outs have been 120 registered or after the lapse of a predetermined time interval. In either event, when the magnet 270 is energized, it will be seen that the latch 269 is lifted and the catch released, so that the spring 268 restores the parts to the position 125 shown in the drawings, and thus renders the machine inoperative for further play.

130 When the operator pulls the bar 247 to the left, as above described, the link 274 also exerts a pull on the crank arm 275, thus rocking the 140 shaft 276 and operating the cam 279. This, acting upon the pin 281, lifts the bar 282 and thus rocks the shafts 285 and 287 through a small angle. The rocking of these shafts serves to restore the run and hit registering mechanism to 145 its normal position, as will hereinafter more clearly appear.

Scoring apparatus

150 As already stated, I provide electrically operated

mechanism for registering and indicating hits, runs and outs. This mechanism is illustrated more particularly in Figs. 28 to 32, inclusive, taken in connection with Fig. 1.

5 Referring to Figs. 28a and Fig. 30a, which illustrates the lower portion of my improved mechanism, it will be seen that I provide an out indicating magnet O and a restoring magnet Q, each comprising a vertically arranged solenoid 288 having a core 289 and supported on a bracket 288a secured to a vertical plate 300.

10 Also, mounted on this plate below and in alignment with the solenoids O and Q are a pair of pilot magnets O' and Q', each comprising a solenoid 290 having a vertically reciprocable core 291.

15 Mounted on the plate 300 between and in alignment with the cores 289 and 291 of each of the solenoids 288 and 290 is a plunger 292 arranged to reciprocate freely through a guide bracket 293 and carrying a block of insulation 294. Set into this block is a metallic contact ring 295.

20 These rings are adapted to engage and close the circuit between two pairs of spring contacts 296, 297 and 298, 299, mounted on the brackets 293. The method in which these contacts are connected will be hereinafter described in detail in connection with the circuit diagram.

25 The upper ends of the cores 289 of the solenoids O and Q are connected through a link 301 with the opposite ends of a walking beam 302 pivoted at 303 to a fixed support. This walking beam carries a lateral projection 304 to which is pivoted one end of a swinging pawl 305, the free end of which is adapted to engage the teeth of a ratchet wheel 306 secured to a shaft 307 journaled in bearings 308 and extending through the plate 300. Beyond this plate there is also rigidly attached to the shaft 307 a wheel 309 having cam teeth 310 in the plane of the wheel and also having one tooth 311 offset from the plane of the wheel.

30 In the embodiment of the invention herein described, the machine has been illustrated as equipped with means by which the electric current is automatically cut off at the end of five innings, that is to say, after thirty outs have been registered. Consequently, the ratchet wheel 306 is illustrated as provided with thirty teeth, one for each out, and the wheel 309 as provided with ten of the teeth 310, one for every third out. The function of these teeth will be described later.

35 The shaft 307 extends through a second bracket 313 and carries at its end a bevel gear 312 meshing with a similar gear 314 carried at the lower end of a vertical shaft 315. This shaft is journaled in a horizontal plate or table 317 supported by posts 318.

40 Resting on the table 317 is a cup-shaped circuit controller or commutator 316 through the center of which the shaft 315 passes. The upper edge of the cup 316 is provided with a series of thirty notches 319, one for each tooth of the ratchet wheel 306, and a resilient detent or spring finger 320 is rigidly attached to the shaft 315 and sweeps over the upper edge of the cup, the end of this finger being arranged to snap into and out of the notches 319 as the shaft revolves in order to prevent overrunning and to insure that the shaft remains in step with the ratchet wheel.

45 A contact arm 321 is secured to the shaft 315 and is adapted to sweep over and engage the inner surface of the cup 316. Set into the wall of the

50 cup, which is of insulating material, and exposed on the inner surface thereof are a series of metallic contacts. The disposition and arrangement of these contacts as well as the connections which they control will more clearly appear from a consideration of the circuit diagram hereinafter described. Suffice it for the present to point out that these contacts include, as shown in Fig. 30a, a central continuous ring 322 and two series of pairs of relatively short contact strips 323 and 324. These strips may be connected with the external circuits of which they form a part by means of binding posts 325 extending through the wall of the cup.

55 Referring now more particularly to Figs. 29 and 30, showing the upper part of my improved registering mechanism, it will be seen that the shaft 315 continues upwardly above the commutator 316, being preferably formed in sections united by a suitable coupling 326, and carries at its upper end an indicating drum 327. This drum constitutes the out register and has displayed on the periphery thereof four horizontal series of figures, all of these series of figures being visible through an opening 328 (see Fig. 1) formed in the front panel 329 of the casing 330 of the 100 scoring apparatus. Associated with the opening 328 on the panel 329 are suitable legends indicating that the two rows of figures appearing at the upper part of the opening 328 relate to the first half inning, while the two rows of figures 105 appearing through the lower part of the opening relate to the last half inning. Further legends are preferably employed to indicate that the uppermost of the two digits appearing through the upper half of the opening indicate the inning, 110 while the lower digit indicates the number of outs. The same is true of the two digits visible through the lower portion of the opening.

115 Referring to Fig. 29, therefore, it will be seen that the digits on the drum 327 are arranged in groups of three, the first and third rows consisting of groups of digits in triplicate, running from 1 to 5, while associated with each such triplicate group and disposed in the second and fourth rows are the digits "0—1—2". Thus, as the drum 120 revolves, the digits will indicate first the number of outs progressively registered during the first half of the first inning, then the number of outs registered during the second half of the first inning, then the outs for the first half of the 125 second inning, and so on until five full innings have been played, whereupon the drum will come to rest in the position shown in Fig. 29, from which it will be seen that what would correspond to the third out of the last half of the fifth inning 130 is the same as the first out for the first half of the first inning of the next game. Furthermore, it will be observed that this out indicating drum rotates always in the same direction and that no resetting mechanism is necessary.

135 As shown in Fig. 1, I preferably form in the panel 329 adjacent the out register, a relatively large translucent arrow or other device, 331, bearing the word "Out" printed thereon, and behind this figure I mount a lamp 332 (see Fig. 29) which lamp is so connected that its circuit is momentarily closed and it is caused to flash each time that the out magnet O is energized, thus visibly indicating to the operator that an out is being registered. This feature, of course, may 140 or may not be employed without interfering with the operation of the rest of the apparatus.

145 In addition to the out register, I provide scoring devices for indicating the runs made during each half of each inning and also for indicating 150

total runs and total hits made by each side. This run and hit registering mechanism is best shown in Figs. 28, 29 and 30.

Referring to these figures, I provide a pair of fixed rods or shafts 333 and 334 supported between a pair of uprights 273 and 333^a, and on these rods or shafts I loosely mount two series of run registering drums or wheels 335 and 336, one for each half inning, and also two sets of drums 337, 338 and 339, 340 for registering total runs and total hits for each side. In addition, I may, if desired, provide another pair of drums 341 and 342 rigidly attached respectively to the hit registering drums 338 and 340, these additional drums being provided on their peripheries with figures arbitrarily indicating "batting average".

Rigid with each of the "drums" 335 to 340, inclusive, is a ratchet wheel 343, by which the drum is driven and held in any position to which it is moved. Furthermore, each of the drums is urged toward the position shown in Fig. 29 by means of a spiral spring 344 secured at one end to the central shaft and at the other end to the drum, as clearly shown in Fig. 30.

The holding means for the drums consists of a pawl 345 mounted on the shaft 285, hereinbefore referred to and provided with a spring 346 by means of which it is yieldingly urged into contact with the ratchet wheel 343. By reference to Fig. 32, it will be seen that the pawls 345 are connected with the shaft 285 by means of a lost motion connection comprising a pin 350 set in the shaft and working in a short slot 349 formed in the hub of the pawl. This slot permits the pawl to swing freely so that it may yield sufficiently to permit the ratchet teeth to pass as the ratchet wheel is driven, but when the shaft 285 is rocked by means of the mechanism shown in Figs. 24 to 27, the pin 350 engages the left hand end of the slot 349 and thus swings the pawl 345 clear of the ratchet wheel, permitting the spring 344 to rotate the drum to zero position.

Associated with each of the lower series of drums 336, etc., is a similar holding pawl 347 mounted on the shaft 287 and provided with springs 348, these pawls also being released by the rocking of the shaft 287, to restore the drums to zero position.

The upper and lower series of drums are rotated toward the right, as viewed in Fig. 30, and in such a direction as to wind the springs 344, by means of driving pawls 351 and 352, respectively, pivotally mounted at the ends of levers 353 and 354 journaled on shafts 355 and 356, and connected at their other ends with the cores 357 and 358 of run and hit solenoids, hereinafter more particularly described.

Referring again to Fig. 30, it will be seen that each of the driving pawls 351 and 352 rides over a fixed rod 359 with which it is held in engagement by means of a spring 360. This arrangement results in a rather peculiar mechanical movement being imparted to the pawls 351 and 352, but which on their upward stroke their end engages the teeth of the ratchet wheels 343 to drive the same, and on their downward stroke they are shifted out of engagement with such teeth by the rods 359, thus leaving the ratchet wheels free to turn under the influence of the springs 344 when the locking pawls 345 and 347 are released.

As will be clearly seen from an inspection of Figs. 28 and 29, I provide ten run registering drums, one for each half inning, and ten sole-

noids for operating them. For the sake of clearness, the solenoids for the first half innings are designated R, while the solenoids for the second half innings are designated R'.

Furthermore, it will be seen that I employ a pair of drums for indicating total runs and total hits for each side and a solenoid for operating each of these drums. For the sake of clearness, the two solenoids for indicating total hits have been designated TH and TH', while the two solenoids for indicating total runs have been designated TR and TR'. These banks of solenoids are supported on brackets 361 and 362 extending between the uprights 273 and 333^a.

Referring once more to Fig. 1, it will be seen that below the out registering window, the front panel 329 of the scoring apparatus is provided with two horizontal rows of openings or windows 363 through which the indications of the above described hit and run registering drums are visible, suitable legends being placed upon the panel adjacent these openings to identify the various indications.

Coming back to Figs. 29a and 30a, it will be seen that below the wheel 309 I provide a pair of parallel levers 364 and 365 both pivotally mounted on a bolt 366 set into the plate 300. The lever 365 lies in the plane of the wheel 309 and is positioned to be engaged and swung on its pivot by each of the teeth 310, while the lever 364 is offset from the plane of the wheel 309 and is positioned to be engaged and swung on its pivot by the laterally projecting tooth 311.

The levers 364 and 365 are provided with downwardly extending arms 367 and 368, respectively, and these arms are arranged to respectively engage the ends of switch rods 369 and 370 slidably mounted in an insulating bracket 371 supported by the plate 300. In addition, the arm 368 may carry a hammer 372 arranged to strike a gong, thus audibly indicating every third out.

Referring to Fig. 31, it will be seen that each of the switch rods 369 and 370 carries a block of insulation 374 and a metallic block 375, and that the rods are normally held in the position shown in the drawings by springs 376. A pair of spring contacts 377 and 378 bear upon the switch elements of rod 369 and a pair of spring contacts 379 and 380 bear upon the switch elements of rod 370. As shown in Fig. 31, the circuit controlled by the contacts 377 and 378 is normally open by reason of the contacts resting upon the insulation 374, this circuit being closed when the rod 369 is pushed toward the right by the engagement of tooth 311 with the lever 364, and the circuit controlled by the spring contacts 379 and 380 is normally closed, because the contacts rest upon the metallic block 375, this circuit being opened when the rod 370 is pushed to the right by the engagement of a tooth 310 with the lever 365. The exact circuits which are controlled by these contacts will be hereinafter more particularly pointed out.

Timing device

As already mentioned, I provide automatic timing mechanism for shutting off the current to the machine after the lapse of a predetermined time interval. This mechanism is shown in detail in Figs. 34 and 36.

Referring again to Fig. 17, in connection with the above figures, it will be seen that there is mounted on the power shaft 124 a belt pulley 381 around which passes a belt 382 engaging and driving a pulley 383 secured to a shaft 384 jour-

- naled in a gear box 385 containing reduction gearing. Also journaled in this gear box and driven at greatly reduced speed is a transverse shaft 386 carrying at its end a worm 387. This 5 meshes with a worm wheel 388 attached to a horizontal shaft 389 journaled in a bracket 390 secured to the gear box, a collar 391 being fixed to the shaft to prevent longitudinal displacement thereof.
- 10 Also rigidly secured to the shaft 389 is a clutch disk 395 adapted to cooperate with a complementary clutch member 396 mounted loosely on the shaft, a spring 397 being interposed between the two clutch members to keep them normally separated. A spiral spring also surrounds the shaft 389 and is anchored at one end to a pin 392 fixed to the bracket 390 and at the other end to a pin 394 set into the side of the clutch member 396.
- 15 20 A sleeve 398 is loosely mounted on the shaft 389 and is adapted to bear at one end against the clutch member 396. The other end of this sleeve has formed therein one or more arcuate cam slots in which ride projections 401 carried by the hub 402 of the lever 404, such hub being loosely journaled on the shaft and held against axial displacement by means of a collar 403. The sleeve 398 is free to slide upon the shaft 389 but is held against rotation by means of a post 399 25 engaging in a slot 400 formed in the sleeve.
- 30 The free end of the lever 404 carries an armature 405 disposed adjacent the pole of an electro-magnet 406 supported on a bracket 407. The clutch member 396 carries at one side a stop pin 408 adapted to engage another pin 409 35 carried by a fixed bracket 410, to limit the rotation of the clutch member 396. This clutch member has a notch formed in its otherwise smooth periphery, such notch providing a low or flat spot 396^a extending through a considerable angle, which flat spot serves as a cam.
- 40 45 A lever 411 is pivoted at 411^a to the bracket 407 and is provided with a tooth or projection 412 which bears on and rides upon the periphery of the clutch member 396, being held against the same by a spring 411^b. As this clutch member turns the lever 411 is raised and lowered by reason of the tooth 412 riding into and out of the cam notch in the periphery of the clutch member.
- 50 The free end of the lever 411 carries two pairs of contact fingers 413 and 414, these fingers being mounted side by side, as shown in Fig. 34, and adapted to simultaneously engage the surface of a rotary switch drum or commutator 415 fixed to the end of a shaft 416 projecting from the gear box 385 and driven by the gearing therein. The speed of this shaft is, of course, much slower than that of the shaft 384 but much faster than that 55 of the shaft 389. In fact, the shaft 389 is geared down to such an extent that it requires a number of minutes to make one revolution. It has been found in practice that seven and a half minutes is a convenient time interval to employ.
- 60 65 The drum or commutator 415, which is made of insulating material, has set into the periphery thereof a pair of metal contacts 417 and 418, these contacts being disposed at diametrically opposite points, as shown in Fig. 35, and also being laterally staggered so that one contact, as, for example, the contact 417 serves to bridge the two contact fingers 413, while the other contact 418 serves to bridge the other two contact fingers 414.
- 70 75 In operation, it will, of course, be understood

that the pulley 383 and shaft 384 commence to revolve immediately that a coin is deposited in the machine and the motor 23 starts up. The commutator 415 is set in rotation but performs no function so long as the contact fingers remain in the elevated position shown in Fig. 35. They are, of course, held in this position by the tooth 412 resting upon the periphery of the clutch member 396. Also as soon as the generator 127 is started, current therefrom energizes the magnet 406, lifts up the armature 405, rocks the hub 402 on the shaft and causes the projections 401 to move the sleeve 398 axially toward the left, as viewed in Fig. 36. This movement pushes the clutch member 396 into engagement with the clutch disk 395 which is slowly rotating, and thus the clutch member 396 is also caused to rotate therewith. As it rotates, it winds up the spring 397 and increases the tension thereof.

80 85 After the clutch member 396 has made nearly one complete revolution in a counter-clockwise direction, as viewed in Fig. 35, the tooth 412 rides down onto the low or flat place 396^a, thus bringing the contact fingers 413 and 414 into engagement with the periphery of the rotating drum 100 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610

Electrical circuits

I have heretofore referred to ball receiving openings or pockets disposed about the playing field and to field contacts operated by the passage of a ball through such pockets. The details of construction of a device of this nature which may be employed are shown in Fig. 33. Beneath one of the openings 7 in the playing field, and also beneath such openings as are designated at 8 in Fig. 1 and disposed around the margin of the field, is mounted a ball receiving chute 419, through which the ball 64 drops by gravity. A swinging lever 420 is pivotally mounted at 421 at one side of the chute and projects into the same so as to be engaged by the ball. Spring contact fingers 422 and 423 are mounted on the side of the chute and are suitably insulated from each other, and it is obvious that when the ball drops through the chute and swings the lever 420 on its pivot so as to press the ends of these contact fingers together, the circuit between such fingers is momentarily closed.

In Figs. 37, 37a, and 37b I have endeavored to illustrate the various electrical circuits and control devices embodied in my improved machine, and although, as is obviously necessary, the mechanical devices appearing in these figures are illustrated in only a conventional or

diagrammatic way, it is thought that the arrangement can be clearly understood from the following description.

Referring first to Fig. 37, all of the conventionally illustrated mechanical elements have been given the same reference numerals as in the other figures, for the purpose of identification.

In addition to the electromagnets illustrated in the other figures and previously described, I employ several other electromagnets and relays which are illustrated only in Fig. 37. One of these is a magnet 424 having an armature 425 arranged to control the circuit from the positive side of the generator to the various field contacts, as hereinafter more particularly pointed out.

Another electrical device is a double advance relay designated DA in Fig. 37, and having an armature 426 adapted to simultaneously engage three different contact points, as shown.

Another electrical device is a pair of electromagnets 427 and 428 between which is mounted a pivoted armature 429 controlling a circuit which includes the track switch magnet 230.

The motor 123 which drives the generator 127 and also serves to move the figures around the bases, is supplied with current from any suitable source through leads 441 and 442, the lead 441 and the return lead 443 extending up to the main control switch and being connected to the spring contacts 262 which are adapted to be bridged by the contact ring 260 on the switch rod 257.

Connected with the generator 127 is a positive lead 430 extending to and through the control switch 425, and to and through the main switch comprising the spring contacts 263 and the contact ring 261 also carried by the switch rod 257.

A positive wire 431 forms a continuation of this lead and joins another wire 432 extending through other devices.

Thus, when the main control switch is moved to the left, as viewed in Fig. 37 and also as viewed in Fig. 24, both pairs of spring contacts 262 and 263 are bridged by the respective rings 260 and 261 and the circuits of both the motor and generator are thereby closed.

Just so soon as the main switch above described is closed, and the motor and generator started, current flows from the positive side of the generator through lead 430, contact ring 261, wires 431 and 432 through magnet 406 and thence through wires 434 and 435 to the negative lead 433 connected with the generator. This energizes magnet 406 and throws into operation the timing mechanism shown in Figs. 34 to 36.

At the same time, current flows from the positive wire 432 through wires 436 and 437 to magnet 42 and thence to the negative lead 433, thus energizing the magnet 42 and unlocking the pitching mechanism, as illustrated in Fig. 5.

At the same time, current also flows from the positive lead 430 up through the wire 438 and magnet 222, this circuit being completed through the switching device 370 and thence through wire 439 to wire 440 connected with the negative side of the line. This energizes the magnet 222 and puts it in condition to hold the runway sections in operative position, as illustrated in Fig. 12.

When one of the contacts 168, illustrated in Fig. 20, bridges the gap between the contact strips 169 and 170, two circuits are simultaneously closed. One of these circuits extends from the positive wire 430 through wire 444, contact strip 170, contact strip 169, wire 445 and wires 446

and 447, through magnet 424, back to the negative side of the line thus energizing the magnet 424 and causing it to attract its armature 425 thereby opening the circuit at this point and cutting the positive lead 430 off from all of the field contacts and control devices fed with current through wire 431. Thus, so long as a contact 168 is down, and the base running mechanism is in operation, the field circuit is open at the point 425 and no additional operations can be produced by the engagement of a ball with any field contact.

The second circuit which is closed through the contact strips 169 and 170 extends through a wire 448 through the solenoid 142 and thence through wire 435 to the negative side of the line. This energizes the solenoid 142 and operatively connects the base running mechanism with the driving motor, as illustrated in Fig. 18. This circuit remains closed until the contact 168 rides up the ramp 172 and clears the ends of the strips 169 and 170, thereupon stopping the base running mechanism.

A wire 449 extends from the positive wire 432 to and through the pilot magnet O' of the out registering solenoid and is then connected with a control wire 450 which extends to the field contacts. It will be noted that the lamp 332, hereinbefore described, is connected across the terminals of the pilot magnet O' so as to be simultaneously energized.

As heretofore mentioned, I provide a number of field contacts similar to that illustrated in Fig. 33, distributed around the field. Some of these contacts are arranged to operate the out register 110 while others control the base hit magnets and still others govern the operation of the sacrifice hits and double advance plays.

Referring to Fig. 37a, the outline of the playing field is indicated at 5 and the outline of the diamond having the usual base positions is shown in broken lines at x. The field contacts which operate the out register and which will hereinafter be referred to as out contacts are indicated by the reference characters OC, and it will be seen 110 that they are distributed in different places, some being scattered over the field just outside the base lines and others being arranged around the margin of the field. One side of all of these out contacts is, as will be seen, connected with the wire 450 above described, while the other side is connected through branch wires 455 and 456 with the negative lead 433. Thus, when the ball drops through any of the pockets where these contacts are located, a circuit will be closed from the positive wire 431 through the pilot magnet O' and wire 450 back to the negative side of the line. This energizes the pilot magnet O' and causes its core 291 to rise and push the switch member 295 upward until it bridges the gap between the spring contacts 298 and 299. Current thereupon flows from the positive wire 432, spring contacts 299 and 298 to and through the out solenoid O and thence by way of wire 440 to the negative lead 433. This energizes the out solenoid 120 and causes it to pull down its core into the position shown in Fig. 37, thus rotating the ratchet wheel 306 one tooth. As the core of the solenoid O comes down, it engages the switch member 295 and pushes it down again, thus 125 breaking its own circuit and leaving the device in position for another operation. From the foregoing, it will be seen that the momentary closing of the field circuit by a ball passing through one of the pockets serves to energize the pilot mag-

net O' and this, by means of the novel switch arrangement illustrated, closes the circuit through the solenoid O which remains closed until opened by the movement of the solenoid core itself. I 5 regard this as a highly novel and important feature for the reason that the closure of a field contact by the ball is of such brief duration that it would not suffice for the proper energization of the solenoid O.

10 The operating solenoid for the pitching device is shown at 91 and when the switch 97 is moved by the cam 57 so as to bridge the contact fingers 99, the circuit of this magnet is closed from the positive wire 436 through the wire 451 to and through the solenoid and thence by way of wire 452 to the negative lead. At the same time that the pitching solenoid is energized, a circuit is also closed from wire 451 through one of the contacts 99 and contact 99^a over the wire 20 453 to and through the pilot Q' of the restoring solenoid Q, the circuit being completed over wires 439 and 440 to the negative lead. Interposed in the circuit just traced are a pair of contact fingers 454^a adapted to be bridged by a contact piece 454 carried by the core of the solenoid Q, these contacts being also illustrated in more detail in Fig. 28a, their purpose being to prevent the energization of the pilot magnet Q' except when the walking beam is in the position shown 25 in Fig. 37. Upon the energization of the pilot magnet Q', as described, its core pushes the corresponding switch member 295 upwardly so as to bridge the contact fingers 296 and 297, whereupon current flows from the positive wire 432 through the solenoid Q and through the contact fingers 296 and 297 to the negative wire 439, thus energizing the solenoid Q and causing it to move the walking beam to the opposite position, thus shifting the pawl 305 (see Fig. 28a) into 30 engagement with another tooth of the ratchet wheel 306 ready for a new operation of the out solenoid. Thus, every time an out contact is engaged by a ball, the ratchet wheel 306 is stepped around one tooth, thus turning the wheel 309 35 and the out registering drum 327, and upon every third out one of the teeth 310 shifts the switch member 370 so as to open the circuit through the wire 438 extending to the holding magnet 222. This causes the holding magnet 222 to release the runway sections and thus dump 40 all base runners below the field.

Upon the thirtieth out, the tooth 311 shifts the switching device 369 so as to close the circuit extending from the positive lead 430 through the locking magnet 270, thus energizing this magnet and causing it to retract its armature 269 and thus release the catch holding the main switch closed, whereupon the spring 268 shifts the main switch into the position shown in the drawings, thus cutting off the current from the motor and also opening the circuit from the generator to the control devices. Simultaneously, of course, the releasing magnet 42 is deprived of current and the pitching mechanism is automatically locked by the pawl 41.

65 Referring now to the base hit magnets designated 1BH, 2BH, etc., it will be seen that one side of all of these magnets is connected by means of a wire 457 with the positive side of the line. Wires extend from the other side of each 70 of the magnets to special field contacts now to be described. From the magnet 1BH extends a wire 458 to a series of one base hit contacts designated 1C, and shown in Fig. 37a, as distributed about the different points in the field. The other

side of these contacts is connected by a branch wire 464 with the negative lead 433.

The magnet 2BH is connected by means of a wire 459 with a series of two base hit contacts designated in Fig. 37a as 2C, the other side of these contacts being connected to the lead 433. 80

Similarly, the magnet 3BH is connected by a wire 460 to a series of three base hit contacts designated 3C, the other side being connected to the lead 433. And finally, the magnet 4BH is connected by means of a wire 461 to a series of four base hit contacts designated 4C. 85

In addition to the out contacts and the various base hit contacts, above described, I provide a number of sacrifice hit contacts SHC and a number of double advance contacts DAC distributed around the field at different points thereon. One side of all of these contacts is connected through branch wires such as 464 with the negative side of the line. The other side of the sacrifice hit contacts is connected by means of the wire 462 with the sacrifice hit magnet SH, which is the same as the magnet 238 shown in Fig. 11. The other side of this magnet is connected by wire 436 with the positive side of the line. The other side of the double advance contacts is connected by means of a wire 465 with the double advance magnet DA, the other side of which is likewise connected with the positive wire 436. 95

100 The hit switch 190, hereinbefore described and illustrated in Fig. 13, is adapted to close a circuit from a wire 466 connected with the negative side of the line through a wire 467 and a wire 468 to the hit registering solenoid TH or TH' in Fig. 37b and thence through a wire 469 or 471 through contacts 323 or 324 and contact ring 322 and arm 321 to the positive side of the line, thus registering a hit. 105

110 It will be observed that there is a series of five pairs of contacts 323 and a series of five pairs of contacts 324, the outer member of each pair of the first series being connected together by a wire 472, which is connected to the wire 469, and the inner member of each pair of the second series 115 being connected together by a wire 474 which is connected with the wire 471. Thus, when the contact arm 321 is in engagement with any of the first series of contacts, the operation of the hit switch serves to energize the hit registering solenoid TH and when the arm 321 is in engagement with any of the inner series of contacts, the operation of the hit switch serves to energize the hit registering solenoid TH'. 125

130 It will be further seen that the inner member of each pair of contacts 323 is connected by a wire such as 473 with one of the run registering solenoids R, while the outer member of each pair of the inner series of contacts 324 is connected by a wire such as 475 with one of the run registering solenoids R'. The other side of each of the solenoids R is connected to a wire 476 and the other side of each of the solenoids R' is connected to a wire 477, these two wires being connected together and to a wire 478 which extends to one pole of the run switch 208, the other pole of which is connected to the negative lead 433. 140

145 It will be further observed by reference to Fig. 37b that the common return wire 476 is connected with one side of the total run registering solenoid TR, the other side of which is connected with the wire 469, and the common return wire 477 is connected with one side of the total run registering solenoid TR', the other side of which is connected with the wire 471. 150

Thus, whenever the arm 321 is in engagement with any of the outer series of contacts and the run switch 208 is crossed, one of the solenoids R and the solenoid TR is energized, while when the 5 arm 321 is in engagement with any of the inner series of contacts and the run switch is closed, one of the solenoids R' and the solenoid TR' is energized. It will, of course, be understood from what has been previously said that the solenoids 10 R, TR and TH are operative during the first half of each inning and the solenoids R', TR' and TH' are operative during the second half of each inning.

The shifting of the hit and run registering circuits from one set of solenoids to the other is accomplished by the arm 321 and the two series of contacts 323 and 324 above described, as is obvious. It may be added, however, that the arm 321 is given a step by step movement by means of 20 the ratchet wheel 306 (see Fig. 28a), and that the size of the steps is such that three of them are required to move the arm over the length of each pair of contacts. Although the arm 321 is shown in Fig. 37b as located between two pairs of contacts, the arrangement is such that it will not stop in this position, but when it moves off of one pair of contacts the throw is sufficient to cause it to engage the next pair before it comes to rest. Thus 25 it is always in engagement with one series of contacts or the other, but never with both at the same time.

Thus it is clear that the arm 321 will remain in engagement with one pair of contacts during the playing of one half of an inning and during the 30 registration of two outs. Upon the third actuation of the out solenoid, however, the arm is shifted to the next pair of contacts, thus engaging alternately the outer and inner series of contacts 323 and 324, thereby transferring the hit and run 35 circuits alternately from one series of solenoids to the other.

From the foregoing, it will be seen that I have provided separate means for registering runs for each half of each inning, as well as means for 40 registering total runs and total hits for each side, and have devised means controlled by the out registering mechanism for shifting from one set of run and hit registering devices to the other.

Referring once more to Fig. 37, it will be seen that the closure of the hit switch 190 also performs another function. It closes a circuit from the 45 positive lead 433 through a wire 470 and the relay 427 back to the negative side of the line by way of wires 467 and 466.

It will further be observed that the energization 50 of the double advance magnet DA causes its armature 426 to close a circuit from wire 466 through relay 428 and wire 479 to the positive side of the line, thus energizing the relay 428.

It will be still further seen that the wire 178 connecting together one of each pair of switch contacts 177 is connected by a wire 480 to the negative side of the line, and the wire 179 connecting together the other members of the pairs 65 of switch contacts 177 is connected to a wire 481 which extends to the armature 429 controlled by the relay magnets 427 and 428 and thence continues through the track switch magnet 230 to the positive side of the line. The wire extending 70 from the relay armature 429 to the magnet 230 also has a branch leading to a contact adapted to be engaged by the armature 426 of the double advance magnet DA.

The third contact engaged by the armature 75 426 of the double advance magnet DA is con-

nected with the wire 459 constituting the two base hit control circuit.

The armature of the sacrifice magnet SH is provided with two contacts, one connected with the wire 458 forming part of the one base hit control circuit and the other being connected with the wire 450 controlling the out registering solenoid.

Referring to the electrical connections of the timing mechanism illustrated in detail in Figs. 34 to 36 and indicated conventionally at the left of Fig. 37, it will be seen that the pair of spring fingers 413 are connected across wires 432 and 453, and that one of the pair of spring fingers 414 is connected by a wire 482 with the wire 450, while the other is connected to the wire 434 which joins the wire 435 extending to the negative side of the line. Thus, when the spring fingers 413 and 414 are brought to bear upon the rotary switch drum 415, the contact segments 417 and 418 alternately and periodically bridge the two pairs of spring fingers. When the fingers 413 are bridged they cross a circuit from the positive wire 432 to the wire 453, thence through the switch 454 through the pilot magnet Q' of the restoring 100 solenoid Q and thence to the negative side of the line.

When the fingers 414 are bridged they close a circuit extending from the positive wire 432 through the pilot magnet O' of the out solenoid 105 O and thence through the wires 482 and 434 to the negative side of the line.

Consequently when, at the expiration of the predetermined time interval, the contact fingers 413 and 414 are brought into engagement with the rotating drum 415, the out solenoid O and the restoring solenoid Q are alternately energized so that the walking beam 302 is oscillated on its pivot and the ratchet wheel 306 is stepped around until it brings the tooth 311 into engagement 110 with the switch member 369, thus closing the circuit through the locking magnet 270, thereby releasing the latch 269 and permitting the spring 268 to shift the main switch to open position, thus stopping the machine. If, on the other hand, 120 thirty outs have been registered before the expiration of the predetermined time interval, then, of course, the timing mechanism including the spring fingers 413 and 414, does not perform any function. This timing mechanism only operates 125 in the event that the game lasts too long, and when it operates it serves to register whatever additional number of outs may be necessary to bring the total up to thirty.

General operation

The general operation of the machine is similar in principle to that of Ropp but differs considerably therefrom in the manner in which the various controlling devices function.

The game is usually played by two persons, one operating the pitching handle P and the other the batting knob B. The pitching crank is preferably geared down so that two revolutions thereof are required to turn the cam 57 around once 140 and close the circuit of the pitching solenoid 91. Thus, a ball is pitched at every second revolution of the pitching crank.

The batter operates the bat to hit the ball out over the playing field. If a ball rolls into 145 an out pocket designated OC on the circuit diagram the pilot magnet O' of the out solenoid O is energized to actuate this solenoid and to turn the out registering drum a distance of one digit so that the numeral 1 will appear at the 150

window in the panel 329 and indicate that there is one out.

Should a hit ball engage one of the one base hit contacts in the field designated by 1C in the circuit diagram, the one base hit magnet 1BH is energized and drops the contact 168 on the contact strips 169 and 170. This closes the circuit through the operating magnet 142, thus causing the motor to drive both the figure carrying chains 118 and the rotating drum 156. At the same time, the magnet 424 is energized, thus interrupting the field circuit at 425 and cutting off the current from the field contacts and from the lock releasing magnet 42, so as to prevent any other operation until the play begun has been completed.

The rotating drum carries the contact 168 around until it runs up the ramp 172 and clears the ends of the contact strips 169 and 170, thus opening the circuit through magnet 142 and stopping the base running mechanism. It will be noted that this mechanism, which is geared to and runs in synchronism with the drum 156 has travelled through one quarter of a revolution, or, in other words, the figures have been moved a distance of one base. The figure going toward first base will be elevated by the track switches 183 and 186 onto the upper runway 189, and as the figure passes the hit switch lever 190 this switch will be closed to register one hit on the drum 338 by energizing the solenoid TH.

If next, with a man on first base, a ball is hit which engages a sacrifice hit contact SHC, it energizes the sacrifice hit magnet SH (shown at 238 in Fig. 11), and this performs three functions. It closes a circuit through the magnet 1BH, thus putting into operation the mechanism which advances the base runners a distance of one base and, at the same time, it closes the circuit through the out pilot magnet O' and thus causes the solenoid O to operate the out registering mechanism. At the same time, as shown in Figs. 11 to 13, the energization of the magnet 238 results in tripping the track switch 186 to inoperative position, thus causing the base runner to be elevated to the lower runway 181 only. Therefore, the result of a sacrifice hit is that the man on base is advanced one base, the figure representing the batter appears above the field and proceeds to first base where he drops off of the end of the runway 181 and disappears, and at the same time the scoring apparatus registers an out. Thus the play is produced exactly as in an actual game.

If, now, the next ball hit engages a contact 4C or, in other words, if it is a home run, the four base hit magnet 4BH will be energized and will drop its contact 168 upon the contact strips 169 and 170 substantially at their end adjacent the gap 171. This will close the circuit through magnets 142 and 424, as before, and the base running mechanism, together with the controlling drum 156 will be driven until the contact 168 travels substantially the full length of the contact strips 169 and 170 off of the end thereof. In other words, the base running mechanism and the control drum move through substantially a complete revolution.

This causes four base running figures to pass home plate. The man previously on base completes his circuit of the bases and comes in toward home plate, operating the run switch 208 as he passes down the runway 207 and registering a run on the face of the drums 235, by reason of the energization of one of the solenoids R.

At the same time, a run is registered on the total run drum 337 by reason of the energization of the solenoid TR.

As the figures travel past home plate beneath the playing field, in response to the four base hit, it is desirable, of course, that only the first one shall be elevated above the playing field, while the remaining three are kept down. The first figure, therefore, is lifted by the track switches 183 and 186, as before. As the contact post or plunger 159, however, passes each of the three switches 177, it closes a circuit through the track switch magnet 230, through the wires 480 and 481, thus throwing the track switch 183 to the inoperative position shown in dotted lines in Fig. 16 and preventing it from elevating the following man. Each figure, however, as it passes, engages the tail 185 of the switch 183, and restores it to normal position. Consequently, the three men following the first remain below the playing field, but the last one leaves the switch in operative position ready to elevate the next man.

From the foregoing, it will be obvious that the extent of movement of the base running mechanism is controlled by the angular position of the particular contact 168 which is brought into engagement with the contact strips 169 and 170. As will be evident, these contacts are dropped into engagement with the strips at one of four different points located respectively one-fourth, one-half, three-quarters and one complete revolution from the end of the strips at which the restoring ramp 172 is formed. Thus, the contacts 168 are selectively brought into engagement with the contact strip at different points, in accordance with the particular base hit magnet which is energized, but they all pass out of engagement with the strips at the same point. Consequently, the extent of movement of the base running mechanism depends on the distance from the ramp and that a contact 168 engages the strips.

It remains to describe the play commonly referred to as a double advance. Let it be supposed that there is a man on first base and that the next ball hit engages one of the double advance contacts DAC. This energizes the double advance magnet DA and causes its armature to close three different circuits. One of these circuits passes through the two base hit magnet 2BH and thus causes the base running mechanism to advance the figures a distance of two bases. Another circuit passes from the positive wire 436 through the track switch magnet 230, thus throwing the track switch 183 to inoperative position, and preventing the elevation of the first man. This first man in passing, however, restores the switch to normal position so that it can elevate the second man above the field. The third circuit passes through and energizes the relay 428, thus causing its armature 429 to interrupt the circuit extending from the switches 177 through the track switch magnet 230, so that this magnet is not energized by the closure of the switches 177 as the drum 156 revolves through half a revolution. Thus, the track switch 183 remains in operative position as the second man approaches, and this second man is therefore elevated, as described.

The effect of the engagement of the ball with a double advance contact, therefore, is that the man already on base is advanced two bases, while the figure representing the batter only goes to first base and stops, just as in a regular game.

As previously explained, upon the registration of the third out, the switch 370 is actuated to

interrupt the circuit of the holding magnet 222, which magnet is normally supplied with current over the wire 438. This results in the releasing of the bell crank lever 216 (Fig. 12), and in permitting the runway sections to turn on their pivots and thus dump all base running figures down below the field, thus clearing the bases for the beginning of the next half inning.

From what has been said, it will be clear that during each half inning the batting and scoring continues until three outs are registered, when the gong rings as an audible indication of the end of the half inning, and the distributor arm 321 and associated contacts then shifts the circuits coming from the hit and run switches to the other series of registering solenoids. Thereupon, the players exchange the control of the pitching and batting handles and the game proceeds with the playing of the second half of the inning, runs, hits and outs being registered as before.

What I claim is:

1. In an automatic baseball game apparatus, a playing field, a playing ball, means for pitching and batting said ball over the field, a registering device, mechanism controlled by said ball after being pitched for scoring successive plays on said registering device, and means responsive either to a predetermined scoring or to the expiration of a predetermined time interval for rendering the apparatus inoperative for further play.

2. In an automatic baseball game apparatus, a playing field, a playing ball, means for pitching and batting said ball over the field, a registering device, mechanism controlled by said ball after being pitched for scoring successive plays on said registering device, and means responsive either to the completion of a predetermined number of innings or to the expiration of a predetermined time interval for rendering the apparatus inoperative for further play.

3. In an automatic baseball game apparatus, a playing field, a playing ball, means for pitching and batting said ball over the field, a registering device, mechanism controlled by said ball after being pitched for scoring successive outs on said registering device, means responsive to the scoring of a predetermined number of outs for rendering the apparatus inoperative for further play, and means brought into operation at the end of a predetermined time interval for automatically further registering whatever outs, in addition to those already scored, may be needed to bring the total up to the number required for rendering the apparatus inoperative.

4. In an electrically operated automatic baseball game apparatus, a playing field having a series of field contacts, a playing ball adapted to selectively engage said contacts, means for pitching and batting said ball over the field, a registering device, a source of current normally connected with said contacts, mechanism controlled by the engagement of said ball with said contacts for scoring successive plays on said registering device, and means responsive either to a predetermined scoring or to the expiration of a predetermined time interval for automatically disconnecting said field contacts from said source of current.

5. In an electrically operated automatic baseball game apparatus, a playing field having bases, base running figures movable around said bases, a motor for moving said figures, means for supplying current to said motor, a playing ball, means for pitching and batting said ball over the field,

a registering device, means controlled by said ball after being pitched for causing said motor to advance said figures predetermined distances around said bases and for scoring successive plays on said registering device, and means responsive either to a predetermined scoring or to the expiration of a predetermined time interval for automatically cutting off the supply of current to said motor.

6. In an electrically operated automatic baseball game apparatus, a playing field having a series of field contacts and also having bases, base running figures movable around said bases, a motor for moving said figures, means for supplying current to said motor, a playing ball adapted to selectively engage said field contacts, means for pitching and batting said ball over the field, a registering device, a source of current normally connected with said field contacts, mechanism controlled by the engagement of said ball with said contacts for causing said motor to advance said figures predetermined distances around said bases and for scoring successive plays on said registering device, and means responsive to a predetermined scoring for automatically and simultaneously cutting off the supply of current to said motor and disconnecting said field contacts from said source of current.

7. In an electrically operated automatic baseball game apparatus, a playing field having a series of field contacts and also having bases, base running figures movable around said bases, a motor for moving said figures, means for supplying current to said motor, a playing ball adapted to selectively engage said field contacts, means for pitching and batting said ball over the field, a registering device, a source of current normally connected with said field contacts, mechanism controlled by the engagement of said ball with said contacts for causing said motor to advance said figures predetermined distances around said bases and for scoring successive plays on said registering device, and means responsive to the expiration of a predetermined time interval for automatically both cutting off the supply of current to said motor and disconnecting said field contacts from said source of current.

8. In an electrically operated automatic baseball game apparatus, a playing field having a series of field contacts, a playing ball adapted to selectively engage said contacts, means for pitching and batting said ball over the field, a registering device, a source of current normally connected with said contacts, mechanism controlled by the engagement of said ball with said contacts for scoring successive plays on said registering device, means responsive to a predetermined scoring for automatically disconnecting said field contacts from said source of current, and coin-controlled manually operated means for restoring such connection.

9. In an electrically operated automatic baseball game apparatus, a playing field having a series of field contacts and also having bases, base running figures movable around said bases, a motor for moving said figures, a circuit for supplying current to said motor, a playing ball adapted to selectively engage said field contacts, means for pitching and batting said ball over the field, a registering device, a circuit connected with said field contacts for supplying current thereto, mechanism controlled by the engagement of said ball with said contacts for causing said motor to advance said figures predetermined distances around the bases, and for scoring successive plays on said

- registering device, means responsive to a predetermined scoring for automatically and simultaneously interrupting both said circuits, and coin-controlled manually operated means for re-establishing said circuits. 5
10. In an automatic baseball game apparatus, a playing field, a playing ball, means for pitching and batting said ball over the field, a registering device, mechanism controlled by said ball after being pitched for scoring successive plays on said registering device, electrically controlled means, including a switch, for locking said pitching means, and means responsive to a predetermined scoring for automatically actuating said switch 10 to render said locking means effective to prevent further operation of said pitching means. 15
11. In an automatic baseball game apparatus, a playing field, a playing ball, means for pitching and batting said ball over the field, a registering device, mechanism controlled by said ball after being pitched for scoring successive plays on said registering device, means for automatically locking said pitching means, electro-magnetic means which, when energized, serves to hold said locking means in release position, means for energizing said electro-magnetic means during normal play, and means responsive to a predetermined scoring for automatically de-energizing said electro-magnetic means to render said locking means 25 effective to prevent further operation of said pitching means. 30
12. In an automatic baseball game apparatus, a playing field, a playing ball, means for pitching and batting said ball over the field, a registering device, mechanism controlled by said ball after being pitched for scoring successive plays on said registering device, electrically controlled means for normally locking said pitching means, means responsive to the deposit of a coin for energizing 35 said electrically controlled means to release said locking means, and means responsive to a predetermined scoring for automatically de-energizing said electrically controlled means to again render said locking means effective. 40
13. In an automatic baseball game apparatus, a playing field, having bases, a playing ball, a pitching device, a batting device for hitting a pitched ball out over the playing field, base running figures, mechanism for advancing the figures around the bases, means controlled by hit 45 balls for operating said mechanism, and means for automatically locking said pitching device during the time said mechanism is in operation. 50
14. In an automatic baseball game apparatus, a playing field, having bases, a playing ball, a pitching device, a batting device for hitting a pitched ball out over the playing field, base running figures, mechanism for advancing the figures around the bases, means controlled by hit 55 balls for operating said mechanism, and means for preventing actuation of said pitching device as long as said mechanism is in operation. 60
15. In an automatic baseball game apparatus, a playing field, having bases, a playing ball, a pitching device, a batting device for hitting a pitched ball out over the playing field, base running figures, mechanism for advancing the figures around the bases, electrically actuated means responsive to hit balls for operating said mechanism, and an electrically controlled device connected with said electrically actuated means for preventing the operation of said pitching device while said mechanism is in action. 65
16. In an automatic baseball game apparatus, a playing field, having bases, a playing ball, a 70
- pitching device, a batting device for hitting a pitched ball out over the playing field, base running figures, mechanism for advancing the figures around the bases, an electric circuit controlled by hit balls and having means for rendering said mechanism operative, and means controlled by said circuit for preventing the actuation of said pitching device so long as said mechanism remains in operation. 80
17. In an electrically operated automatic baseball game apparatus, a playing field having a series of field contacts and also having bases, base running figures movable around said bases, a playing ball adapted to selectively engage said contacts, a source of current normally connected with said field contacts, mechanism controlled by the engagement of said ball with said contacts for advancing said figures predetermined distances around said bases, and means for automatically disconnecting said contacts from said source of current during the time said advancing mechanism is in operation. 85
18. In an electrically operated automatic baseball game apparatus, a playing field having a series of field contacts and also having bases, base running figures movable around said bases, a playing ball adapted to selectively engage said contacts, a source of current normally connected with said field contacts, a registering device, mechanism controlled by the engagement of said ball with certain of said contacts for advancing said figures around said bases, and with others of said contacts for scoring successive outs on said registering device, and means operated by the engagement of the ball with one of said figure advancing contacts for automatically disconnecting said out scoring contacts from said source of current. 90
19. In a miniature base ball game apparatus, a playing field, a bat mounted to swing over and close to the field so as to meet a ball when rolled toward the bat on the field, a cabinet in which the playing field is enclosed, said cabinet having a removable panel, a manually rotatable handle journaled in said panel, operating mechanism for said bat, and a detachable and flexible coupling between said mechanism and said handle, whereby the latter may be connected to and disconnected from the former. 110
20. In a miniature baseball game apparatus, a playing field, mechanism for pitching a ball over the field, a manually operable handle for actuating said pitching mechanism, means for locking said pitching mechanism, and a safety device connecting said handle and mechanism capable of transmitting sufficient force to normally operate said pitching mechanism but constructed to slip should an attempt be made to move said handle when said mechanism is locked. 120
21. In a miniature baseball game apparatus, a playing field, mechanism for pitching a ball over the field, a manually rotatable shaft for operating said pitching mechanism, means for locking said pitching mechanism, and a clutch device interposed between said shaft and said mechanism, said clutch device being capable of transmitting sufficient torque to normally actuate said mechanism, but being constructed to slip should said shaft be rotated when said pitching mechanism is locked. 135
22. In a baseball game apparatus, a playing field, a playing ball, a pivotally mounted pitching arm for pitching the ball over the field, a solenoid for swinging said arm on its pivot, and 140
- 75

- manually operated means for controlling the energization of said solenoid.
23. In a baseball game apparatus, a playing field, a playing ball, a pivotally mounted pitching arm for pitching the ball over the field, electrically actuated means for swinging said arm on its pivot, mechanism for feeding the ball to the pitching arm, and a single manual means for both operating said feeding mechanism and energizing said electrically actuated means.
24. In a baseball game apparatus, a playing field, a playing ball, a pivotally mounted pitching arm for pitching the ball over the field, electrically actuated means for swinging said arm on its pivot, a manually movable member, and connections whereby a single movement of said member serves both to feed the ball to the pitching arm and to energize said electrically actuated means.
25. In an automatic baseball game apparatus, a playing field, playing balls, a pivotally mounted pitching arm for pitching a ball over the field, electrically actuated means for swinging said arm on its pivot, a switch controlling said means, a manually operated member, and means whereby said member serves by its initial movement to feed a ball to said pitching arm and by a further movement to close said switch.
26. In an automatic baseball game apparatus, a playing field, playing balls, a pivotally mounted pitching arm for pitching a ball over the field, electrically actuated means for swinging said arm on its pivot, a switch controlling said means, an operating element, manual means for imparting a relatively slow initial movement to said element, means whereby said element serves, during such relatively slow initial movement to feed a ball to said pitching arm, means operative upon completion of such feeding movement to impart to said element a further and relatively quick movement with a snap action, and means whereby said element serves, during such quick movement, to close said switch.
27. In an automatic baseball game apparatus, a playing field, playing balls, a pivotally mounted pitching arm for pitching a ball over the field, electrically actuated means for swinging said arm on its pivot, a switch controlling said means, a rotary cam member, manual means for rotating said cam member, means operated by the initial movement of said cam member for feeding a ball to said pitching arm, and means operated by a further movement of said cam member in the same direction for closing said switch.
28. In an automatic baseball game apparatus, a playing field, playing balls, a pivotally mounted pitching arm for pitching a ball over the field, electrically actuated means for swinging said arm on its pivot, a switch controlling said means, a vertical guide in which the balls are held in a column, the upper end of said guide being arranged to deliver the balls to said pitching arm, a manually operated cam member, means whereby said cam member serves, during its initial movement to elevate said column so as to discharge a ball from the upper end of said guide into said pitching arm, and means whereby said cam member serves, by a further movement in the same direction, to close said switch and thus swing said arm on its pivot.
29. In a baseball game apparatus, a playing field, a playing ball, a pivotally mounted pitching arm for pitching the ball over the field, a solenoid for swinging said arm on its pivot, a switch controlling said solenoid, manual means for closing said switch to actuate the pitching arm, and means operated by the said solenoid itself for opening said switch.
30. In an automatic baseball game apparatus, a playing field, a playing ball, a pitching arm positioned beneath the surface of the playing field, a pivoted trap-door above the pitching arm flush with the surface of the playing field, mechanism for operating the pitching arm to pitch the ball over the field, and means mechanically connecting said pitching arm and trap-door whereby the latter is positively opened and shut by the movement of the former.
31. In an automatic baseball game apparatus, a playing field, a playing ball, a pitching arm positioned beneath the surface of the playing field, a pivoted trap-door above the pitching arm flush with the surface of the playing field and having a depending portion, mechanism for operating the pitching arm to pitch the ball over the field, and a link connecting the depending portion of said trap-door with said pitching arm, whereby said door and arm move in synchronism.
32. In an automatic baseball game machine, a playing field having bases, base running figures, mechanism for advancing the figures around the bases, said mechanism including a traveling device supporting the figures and adapted to be driven, a constantly running motor, normally inoperative gearing between said motor and traveling device, and control apparatus for rendering said gearing operative for various lengths of time to drive said device and advance the figures from one to four bases, selectively.
33. In an automatic baseball game machine, a playing field having bases, base running figures, mechanism for advancing the figures around the bases, said mechanism including a traveling device supporting the figures and adapted to be driven, a constantly running motor, normally inoperative gearing between said motor and traveling device, and electromagnetically actuated control apparatus for rendering said gearing operative for various lengths of time to drive said device and advance the figures from one to four bases, selectively.
34. In an automatic baseball game machine, a playing field having bases, a playing ball, means for pitching and batting the ball over the field, base running figures, mechanism for advancing said figures around the bases, and means responsive to a batted ball for operating said mechanism, said means including stationary control electromagnets, and control contacts therefor distributed around the field for engagement by a batted ball, movable armatures for said electromagnets, and a rotary support on which said armatures are mounted.
35. In an automatic baseball game machine, a playing field having bases, a playing ball, means for pitching and batting the ball over the field, base running figures, mechanism for advancing said figures around the bases, and means responsive to a batted ball for operating said mechanism, said means including field contacts and base-hit electromagnets controlled thereby, an operating circuit, means governed by said electromagnets for closing the same, said closing means comprising fixed and movable parts, said electromagnets being fixed and having movable armatures, and a traveling support on which said armatures and the movable parts of said circuit closing means are mounted.
36. In an automatic baseball game machine, a playing field having bases, a playing ball, means for pitching and batting the ball over the field,

- base running figures, mechanism for advancing said figures around the bases, and means responsive to a batted ball for operating said mechanism, said means including control electromagnets and control contacts therefor distributed around the field for engagement by a batted ball, an operating circuit comprising an elongated contact strip, a plurality of movable contact members each adapted to engage said strip 5 and individually controlled by said respective electromagnets, a carrier on which said contact members are mounted in spaced relation, and means for causing said carrier to travel in such a direction as to move said contact members 10 longitudinally of said strip.
37. In an automatic baseball game machine, a playing field having bases, a playing ball, means for pitching and batting the ball over the field, base running figures, mechanism for advancing said figures around the bases, and means responsive to a batted ball for operating said mechanism, said means including control electromagnets and control contacts therefor distributed around the field for engagement by a 20 batted ball, an operating circuit comprising an elongated contact strip, a plurality of movable contact members each adapted to engage said strip at different points in the length thereof and close said circuit, means for bringing a particular one of said contact members into engagement with said strip dependent upon which particular one of said electromagnets is energized, and means controlled by said circuit for moving the engaged contact member from the 30 point of engagement along said strip to the end thereof.
38. In an automatic baseball game machine, a playing field, having bases, a playing ball, means for pitching the ball, a batting device 40 for hitting the ball out over the field, base running figures, mechanism for advancing the figures around the bases, and means responsive to a hit ball for operating said mechanism, said means including an operating circuit, a controller 45 therefor comprising a fixed contact strip and a plurality of movable contact members adapted to engage the same at different points in the length thereof, to close said circuit, means for bringing a particular one of said contact members into engagement with said strip according to the particular part of the field the ball is hit to, and means operating in synchronism with said figure advancing mechanism for moving the engaged contact member from the point of engagement along said strip to the end thereof.
39. In an automatic baseball game machine, a playing field having bases, base running figures, mechanism for moving said figures around the bases, and means for operating said mechanism, 60 said means including an operating circuit, a controller therefor comprising a plurality of electromagnets, a stationary arcuate contact strip, a support mounted to rotate adjacent and parallel with the plane of said strip, a plurality of contact members, one for each electromagnet, carried by said support in spaced relation and adapted to engage said strip at different points, to close said circuit, means whereby energization of any one of said electromagnets will cause the respective contact member to engage said strip, and means for rotating said support in synchronism with said figure moving mechanism.
40. In an automatic baseball game machine, a playing field having bases, base running figures, 70 mechanism for moving said figures around the bases, and means for operating said mechanism, 75
- bases, and means for operating said mechanism, said means including an operating circuit, a controller therefor comprising a plurality of electromagnets, an arcuate contact strip, a support mounted to rotate adjacent and parallel with the plane of said strip, a plurality of contact members, one for each electromagnet, carried by said support in spaced relation and adapted to engage said strip at different points, to close said circuit, means whereby energization of any one of said electromagnets will cause the respective contact member to engage said strip, means put into operation by the engagement of a contact member with the strip for rotating said support to cause the engaged member to travel along said strip, and means for disengaging said member from said strip when it reaches a predetermined point in its travel.
41. In an automatic baseball game machine, a playing field having bases, base running figures, mechanism for moving said figures around the bases, and means for operating said mechanism, said means including an operating circuit, a controller therefor comprising a plurality of electromagnets, an arcuate contact strip, a support 80 mounted to rotate adjacent and parallel with the plane of said strip, a plurality of contact members, one for each electromagnet, carried by said support in spaced relation and adapted to engage said strip at different points, to close said circuit, 85 said members being biased toward said strip, means for holding said members out of engagement with said strip, means whereby energization of any one of said electromagnets will release the holding means of the corresponding contact member, and cause it to engage the strip, means put into operation by the engagement of a contact member with said strip for rotating said support to cause the engaged contact member to travel along said strip, and means for automatically disengaging the contact member from said strip at a certain point in its travel and restoring it to its original position relative to said support and holding means.
42. In an automatic baseball game machine, a playing field having bases, base running figures, mechanism for moving said figures around the bases, and means for operating said mechanism, said means including an operating circuit, a controller therefor comprising an arcuate contact strip, a rotary support mounted concentrically of said strip, a plurality of spaced contact members carried by said support and each adapted to engage said strip to close said circuit, automatic means for bringing any selected one of said contact members into engagement with said strip at a predetermined point thereof, the point of engagement for each contact member being different, means for thereupon rotating said support to cause the engaged contact to travel along the strip, and means for automatically removing every engaged contact member from the strip at the same point thereof.
43. In a miniature baseball game apparatus, a playing field having bases, base running figures, mechanism for advancing said figures around the bases, a runway extending around the base line below the field for supporting said figures above the field while being advanced, said runway comprising portions biased toward and automatically movable into a position in which they no longer support the figures but permit them to drop below the field, and an electromagnet for holding said runway portions in figure-supporting position.
44. In a miniature baseball game apparatus, a

- playing field having bases, base running figures, mechanism for advancing said figures around the bases, a runway extending around the base line below the field for supporting said figures above the field while being advanced, said runway comprising portions biased toward and automatically movable into a position in which they no longer support the figures but permit them to drop below the field, means operated by a runner traveling from home plate toward first base for moving said runway portions to figure supporting position, and an electromagnet for holding said runway portions in such positions. 45. In a miniature baseball game apparatus, a playing field having bases, base running figures, mechanism for advancing said figures around the bases, a runway extending around the base line below the field for supporting said figures above the field while being advanced, said runway comprising portions automatically movable into a position in which they no longer support the figures but permit them to drop below the field, and an electromagnet for holding said runway portions in figure-supporting position by direct magnetic attraction thereon. 46. In a miniature baseball game apparatus, a playing field having bases, base running figures, mechanism for advancing said figures around the bases, a runway extending around the base line below the field for supporting said figures above the field while being advanced, said runway comprising portions automatically movable into a position in which they no longer support the figures but permit them to drop below the field, an electromagnet for holding said runway portions in figure supporting position, a scoring device, and means whereby said scoring device automatically controls said electromagnet. 47. In a miniature baseball game apparatus, a playing field having bases, base running figures, mechanism for advancing said figures around the bases, a runway extending around the base line below the field for supporting said figures above the field while being advanced, said runway comprising portions automatically movable into a position in which they no longer support the figures but permit them to drop below the field, an electromagnet for holding said runway portions in figure supporting position, mechanism for automatically registering outs, and means responsive to the registration of a predetermined number of outs for de-energizing said electromagnet. 48. In a miniature baseball game apparatus, a playing field having bases, base running figures, mechanism for advancing said figures around the bases, a runway extending around the base line below the field for supporting said figures above the field while being advanced, said runway comprising sections disposed between the respective bases, each of said sections being pivotally mounted to rotate about a longitudinal axis into a position in which it will no longer support the figures, but will permit them to drop below the field, and means for controlling the position of said sections. 49. In a miniature baseball game apparatus, a playing field having bases, base running figures, mechanism for advancing said figures around the bases, a runway extending around the base line below the field for supporting said figures above the field while being advanced, said runway comprising sections disposed between the respective bases, each of said sections being pivotally mounted to rotate about a longitudinal axis into a position in which it will no longer support the figures, but will permit them to drop below the field, and means for controlling the position of said sections. 50. In an automatic baseball game apparatus, a playing field having bases, base running figures, mechanism for supporting the figures beneath the field and for advancing them around the bases, and means for selectively elevating the advancing figures above the field to either one of two different levels. 51. In an automatic baseball game apparatus, a playing field having bases, base running figures, mechanism for supporting the figures beneath the field and for advancing them around the bases, a scoring device, means for selectively elevating the advancing figures above the field to either one of two different levels, and means whereby the figures advancing at one level operate said scoring device while those advancing at the other level do not operate it. 52. In an automatic baseball game apparatus, a playing field having bases, base running figures, mechanism for supporting the figures beneath the field and for advancing them around the bases, a hit registering device, means for selectively elevating to either one of two different levels above the field the figures advancing from home plate toward first base, and means whereby the figures advancing on one level only operate said hit registering device. 53. In an automatic baseball game apparatus, a playing field having bases, base running figures, mechanism for supporting the figures beneath the field and for advancing them around the bases, a hit registering device, means for selectively elevating to either one of two different levels above the field the figures advancing from home plate toward first base, and means whereby the figures advancing on one level operate said hit registering device and progress toward second base, while the figures advancing on the other level do not operate said hit registering device and drop below the field upon reaching first base. 54. In an automatic base ball game apparatus, a playing field having bases, base running figures, mechanism for supporting the figures beneath the field and for advancing them around the bases, a pair of runways disposed beneath the field at different levels, one of said runways terminating adjacent first base, and the other runway continuing around the bases, means for selectively elevating the advancing figures to one or the other of said runways, whereby said figures either progress toward second base or drop below the field when reaching first base, in accordance with which runway they are traveling on. 55. In an automatic baseball game apparatus, a playing field having bases, base running figures, mechanism for supporting the figures beneath the field and for advancing them around the bases, a pair of runways disposed beneath the field at different levels, one of said runways terminating adjacent first base, and the other runway continuing around the bases, means for selectively elevating the advancing figures to one or the other of said runways, a hit registering device, and means whereby the figures advancing on said continuing runway only operate said hit registering device. 56. In a automatic baseball game apparatus, a playing field having bases, base running figures, mechanism for supporting the figures beneath the field and for advancing them around the bases, an electrically actuated hit registering device, a

switch for controlling the same located between home plate and first base, means for selectively elevating the advancing figures above the field to either of two different levels, and means whereby the figures advancing on one level, operate said switch, while those advancing on the other level pass by said switch without operating the same.

57. In an automatic baseball game apparatus, a playing field having bases, base running figures, mechanism for supporting the figures beneath the field and for advancing them around the bases, means between home plate and first base for elevating said figures to either one of two different levels above the field, the figures elevated to one level advancing around the bases, while those elevated to the other level drop out of play before reaching first base, means between third base and home plate for lowering again below the field all elevated figures reaching that point, and means whereby all figures pass the home plate position at the same level beneath the field, from which level they may be lifted by said elevating means.

58. In an automatic baseball game apparatus, a playing field having bases, a playing ball, means for pitching and batting the ball over the field, hit and sacrifice hit control devices distributed around the field, base running figures, mechanism for supporting the figures and for advancing them simultaneously around the bases in response to hit balls, said figures being normally beneath the field, means for elevating certain selected figures above the field as they advance, a lower runway between home plate and first base terminating at first base, an upper runway parallel therewith and continuing around the base lines, means responsive to the engagement of a batted ball with a sacrifice hit control device for causing said elevating means to raise a base running figure above the field to said lower runway, whereby said figure drops off the end of said runway at first base, and disappears beneath the field, and means responsive to the engagement of a batted ball with a hit control device for causing said elevating means to raise a figure up to said upper runway, whereby said figure may continue around the bases in its elevated position.

59. In an automatic baseball game apparatus, a playing field, a playing ball, devices for pitching and batting said ball over the field, field contacts adapted to be engaged by the ball, out registering mechanism, a solenoid for operating said mechanism, a pilot magnet connected to said field contacts for momentary energization by the engagement of the ball therewith, and means actuated by such momentary energization of said pilot magnet for supplying current to said solenoid and maintaining such supply until after the solenoid core has completed its stroke.

60. In an automatic baseball game apparatus, a playing field, a playing ball, devices for pitching and batting said ball over the field, field contacts adapted to be engaged by the ball, out registering mechanism, a solenoid for operating said mechanism, a pilot magnet connected to said field contacts for momentary energization by the engagement of the ball therewith, and means actuated by such momentary energization of said pilot magnet for supplying current to said solenoid for a period of time sufficiently long to cause the same to operate.

61. In an automatic baseball game apparatus, a playing field, a playing ball, devices for pitching and batting said ball over the field, field contacts

adapted to be engaged by the ball, out registering mechanism, a solenoid for operating said mechanism, and means actuated by the momentary engagement of the ball with one of said field contacts for energizing said solenoid during a longer period than the engagement of the ball with said field contacts.

62. In an automatic baseball game apparatus, a playing field, a playing ball, devices for pitching and batting said ball over the field, field contacts adapted to be engaged by the ball, out registering mechanism, a solenoid for operating said mechanism, and means actuated by the engagement of the ball with one of said field contacts, for supplying current to said solenoid, and means independent of said field contact for continuing the supply of current for a period of time sufficient to operate said solenoid.

63. In an automatic baseball game apparatus, a playing field, a playing ball, devices for pitching and batting said ball over the field, field contacts adapted to be engaged by the ball, out registering mechanism, a solenoid for operating said mechanism, means actuated by the momentary engagement of the ball with one of said field contacts for closing the circuit of said solenoid to supply current thereto, and means actuated by the movement of the solenoid core itself for opening said circuit.

64. In an automatic baseball game apparatus, a playing field, a playing ball, pitching mechanism, batting mechanism, field contacts adapted to be engaged by the ball, an out registering device, a pair of electromagnets for jointly operating said device, means responsive to the engagement of the ball with one of said field contacts for energizing one of said electromagnets, and manually controlled means for energizing the other.

65. In an automatic baseball game apparatus, a playing field, a playing ball, pitching mechanism, batting mechanism, field contacts adapted to be engaged by the ball, an out registering device, a pair of electromagnets for jointly operating said device, means responsive to the engagement of the ball with one of said field contacts for energizing one of said electromagnets, and means controlled by the pitching mechanism for energizing the other.

66. In an automatic baseball game apparatus, a playing field, a playing ball, pitching mechanism, batting mechanism, base running figures, means responsive to a hit ball for advancing said figures around the bases, scoring mechanism, electrically actuated means controlled by said ball after being pitched for operating said scoring mechanism to register outs, and electrically actuated means, controlled by said base running figures, for operating said scoring mechanism to register hits and runs.

67. In an automatic baseball game machine, a playing field, a playing ball, pitching apparatus, batting apparatus for hitting a pitched ball out over the field, scoring apparatus for registering runs for the first half of each inning individually, separate scoring apparatus for registering runs for the second half of each inning individually, a common operating means for said two apparatus, and means for shifting the connections of said operating means from one scoring apparatus to the other.

68. In an automatic baseball game machine, a playing field, a playing ball, pitching apparatus, batting apparatus for hitting a pitched ball out over the field, scoring apparatus for registering runs for the first half of each inning in-

dividually, separate scoring apparatus for registering runs for the second half of each inning individually, a common operating means for said two apparatus, means responsive to pitched balls for registering outs, and means controlled by said out registering means for shifting the connections of said operating means from one scoring apparatus to the other.

69. In an automatic baseball game machine, 10 a playing field, a playing ball, pitching apparatus, batting apparatus for hitting a pitched ball out over the field, two sets of electrically actuated scoring devices, each set serving to register runs for each of a series of individual half innings, a 15 run switch and circuit connected therewith for operating said scoring devices, out registering mechanism, and means actuated by said out registering mechanism for shifting the electrical connections of said run switch from one set of scoring devices to the other, at the occurrence of every 20 third out.

70. In an automatic baseball game machine, 25 a playing field having bases, pitching and batting apparatus, base running figures, means, including a motor, for advancing said figures around the bases, and timing mechanism comprising gearing driven by said motor for automatically rendering the machine inoperative for further play after the expiration of a predetermined time interval.

71. In an automatic baseball game machine, 30 a playing field, a playing ball, means for pitching and batting said ball over the field, a registering device, electromagnetically operated mechanism controlled by said ball after being pitched for actuating said device for scoring successive outs, means responsive to the scoring of a predetermined number of outs for rendering the machine inoperative for further play, and means 35 brought into operation at the end of a predetermined time interval for automatically and periodically energizing said electromagnetically operated mechanism to further register whatever outs, in addition to those already scored, may be 40 needed to bring the total up to the number required for rendering the machine inoperative.

72. In an automatic baseball game machine, 45 a playing field, movable figures, mechanism including an electric motor for moving said figures, a circuit for supplying current to said motor, a playing ball, means for pitching and batting said ball over the field, a registering device, mechanism controlled by said ball for scoring successive plays on said registering device, means 50 for locking said pitching means, and means responsive to a predetermined scoring for automatically rendering said locking means effective to prevent further operation of said pitching means, and interrupting said motor circuit.

73. In an automatic baseball game machine, 55 a playing field having a series of field contacts, a playing ball adapted to selectively engage said contacts, means for pitching and batting said ball over the field, a registering device, a motor-generator set, a circuit for supplying current to 60 said motor, circuit connections between said field contacts and registering device, supplied with current from said generator, whereby, when said motor is running, engagement of said ball with said field contacts serves to score successive plays 65 on said registering device, means for locking said pitching means, and means responsive to a predetermined scoring for automatically rendering said locking means effective to prevent further 70 operation of said pitching means and simulta-

neously disconnecting said motor from its supply circuit.

74. In an automatic baseball game machine, a 80 playing field, operating mechanism including an electric motor, a circuit for supplying current to said motor, a playing ball, means for pitching said ball over the field, means for locking said pitching means, and means responsive to the occurrence of a predetermined condition for automatically rendering said locking means effective to prevent further actuation of said pitching means, and simultaneously interrupting said motor circuit.

75. In an electrically operated automatic baseball game apparatus, a playing field having a 90 series of field contacts and also having bases, base running figures movable around said bases, a playing ball adapted to selectively engage said contacts, a source of current normally connected with said field contacts, a registering device, 95 mechanism controlled by the engagement of said ball with certain of said contacts for advancing said figures around said bases, and with others of said contacts for scoring successive outs on said registering device, and means operated by the 100 engagement of the ball with one of said figure advancing contacts for automatically disconnecting all of said contacts from said source of current.

76. In an automatic baseball game machine, 105 a playing field having bases, base running figures, mechanism for advancing the figures around the bases, said mechanism including a traveling device supporting the figures and adapted to be driven, a constantly running motor, control apparatus; speed reduction gearing through which said motor drives both said traveling device and said control apparatus, a rotary power transmitting element interposed between said motor and reduction gearing and adapted to be moved to 110 connect or disconnect said parts, said element being stationary when the parts are disconnected, whereby it exerts no drag upon the driven part, and means governed by said control apparatus for moving said element to connecting 115 position to advance said figures a predetermined amount, and then moving said element to idle position.

77. In an automatic baseball game machine, a 125 playing field, four base running figures, mechanism for moving said figures around the bases in equally spaced relation, means for operating said mechanism including an operating circuit, a controller therefor comprising four electro-magnets, an arcuate contact strip, a support mounted to 130 rotate adjacent and parallel with the plane of said strip, four contact members, one for each electro-magnet, carried by said support and uniformly spaced around the same 90° apart, said contact members adapted to engage said strip at 135 different points to close said circuit, means whereby energization of any one of said electro-magnets will cause the respective contact member to engage said strip, and means for rotating said support in synchronism with said figure moving 140 mechanism so that said contact members and figures travel through equal angular displacements.

78. In an automatic baseball game machine, a 145 playing field having bases, base running figures, mechanism for moving said figures around the bases, and means for operating said mechanism, said means including an operating circuit, a controller therefor comprising a plurality of electro-magnets, a stationary arcuate contact strip, a 150

support mounted to rotate adjacent and parallel with the plane of said strip, a plurality of contact members, one for each electro-magnet, carried by said support in spaced relation and adapted to engage said strip at different points, to close said circuit, the number of contact members and electro-magnets being the same as the number of base running figures, means whereby energization of any one of said electro-magnets will cause the respective contact member to engage said strip, and means for rotating said support with the same angular velocity as said figure moving mechanism.

79. In an automatic baseball game machine, a playing field having bases, base running figures, mechanism for moving said figures around the bases, and means for operating said mechanism, said means including an operating circuit, a controller therefor comprising a plurality of electro-magnets, an arcuate contact strip, a support mounted to rotate adjacent and parallel with the plane of said strip, a plurality of contact members, one for each electro-magnet, carried by said support in spaced relation and adapted to engage said strip at different points, to close said circuit, said members being biased toward said strip, means for holding said members out of engagement with said strip, means whereby energization of any one of said electro-magnets will release the holding means of the corresponding contact member, and cause it to engage the strip, means put into operation by the engagement of a contact member with said strip for rotating said support to cause the engaged contact member to travel along said strip, and means for automatically disengaging the contact member from said strip at a certain point in its travel and restoring it to its original position relative to said support and holding means, before the end of the strip is reached.

80. In an automatic baseball game machine, a playing field having bases, base running figures, mechanism for moving said figures around the

bases, and means for operating said mechanism, said means including an operating circuit, a controller therefor comprising a plurality of electro-magnets, an arcuate contact strip, a support mounted to rotate adjacent and parallel with the plane of said strip, a plurality of contact members, one for each electro-magnet, carried by said support in spaced relation and adapted to engage said strip at different points, to close said circuit, said members being biased toward said strip, means for holding said members out of engagement with said strip, means whereby energization of any one of said electro-magnets will release the holding means of the corresponding contact member, and cause it to engage the strip, means put into operation by the engagement of a contact member with said strip for rotating said support to cause the engaged contact member to travel along said strip, and means for automatically disengaging the contact member from said strip at a certain point in its travel and restoring it to its original position relative to said support and holding means, before the end of the strip is reached.

81. In an automatic baseball game machine, a playing field, a playing ball, pitching apparatus, batting apparatus for hitting a pitched ball out over the field, scoring apparatus for registering runs for the first half of each inning individually, separate scoring apparatus for registering runs for the second half of each inning individually, a common operating means for said two apparatus, means responsive to pitched balls for registering outs, said out registering means comprising a rotary drum, a shaft on which said drum is mounted, ball controlled means for rotating said shaft and "out" drum continuously in one direction as successive innings are played, and means actuated by said shaft for shifting the connections of said common operating means from one scoring apparatus to the other.
